UNITED STATES PATENT OFFICE.

ALBERT C. POWELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed December 3, 1923. Serial No. 678,141.

To all whom it may concern:

Be it known that I, ALBERT C. POWELL, a citizen of the United States of America, residing at New York, in the county of Bronx and State of New York, have invented certain new and useful Improvements in Telephone-Exchange Systems, of which the following is a full, clear, concise, and exact description.

10 This invention relates to telephone exchange systems, and particularly to those systems wherein mechanical switching apparatus is employed in the establishment of talking connections.

15 In switching areas including both manual offices and automatic offices, where provision is made for the extension of calls made in an automatic office to any of the out-lying offices either of the manual or automatic type, it is customary to cause the 20 number of a wanted line terminating in a manual office to be displayed before the operator of such office by means of a call indicator which is controlled from an office 25 sender in the calling automatic office. The operator noting the displayed number then completes the call by inserting the plug in which the trunk incoming from the calling automatic office terminates in the jack of 30 the wanted line.

In such an exchange area it is desirable to permit incoming toll calls to be extended to either manual or automatic offices and terminated therein by employing the same 35 equipment in the terminating office as is employed on intra-exchange calls. The completion of such toll calls may be accomplished in much the same manner as intra-exchange calls are established between a 40 calling manual office and either an automatic or manual terminating office by the employment of key indicator mechanism at the toll switching office of the exchange. If the wanted line terminates in an automatic office of the exchange the toll operator may then employ key indicator mechanism of substantially the same type as disclosed in the Patent No. 1,513,362, issued to L. M. Allen, October 28, 1924, for selecting 45 an idle trunk extending to the desired office and for setting the automatic switches of such office to select the wanted line.

If, however, the wanted line terminates in a manual office, then provision must be 50 made at the toll office for controlling the

call indicator equipment at the desired manual office to indicate to the operator the number of the line desired. This is accomplished in accordance with the present invention by providing additional key indicator equipment at the toll office which functions not only to select an idle trunk extending to the desired manual office, but also functions under the control of a toll operator to control the operation of call indicator equipment at the manual office.

At the toll office there are therefore provided a plurality of toll operators' positions, each of which has access to a plurality of groups of outgoing trunks, one group extending to each of the distant manual offices served. Each position is further equipped with a sender controlling keyboard, a set of office keys and a set of indicating lamps for trunk identification. There are also located at the toll office a group of register senders common to the use of the operators and serving to transmit wanted line designations for registration upon call indicators in distant manual offices. In order that an idle sender may be taken for use to extend a call and to associate such sender with the keyboard at the operator's position concerned, and also with an idle trunk in the particular group leading to the wanted manual office, a plurality of switching units is employed. These units comprise three distinct parts, a sender selector for selecting an idle sender, trunk selectors for choosing an idle outgoing trunk, and a plurality of operators' position selectors. When one of the operators wishes to extend a call, an allotted one of these switching units is set in motion, the three different types of switches comprising the units, all acting simultaneously.

The object of the invention is therefore the provision in a system of the character outlined, of means for enabling operators to control the extension of calls to manual offices of an exchange area equipped with call indicator mechanism, through the employment of the regular equipment of the terminating manual offices.

A feature of the invention is the provision of a sender for association with a switching unit of a calling manual office, which is arranged to register the designation of a wanted line under the control of a keyboard of the operator's position

at the time associated with the switching unit, and to transmit codes of impulses of the proper character over the trunk circuit selected by the switching unit for causing 5 the registration of the wanted line designation upon a call indicator in the office in which the wanted line terminates.

A further feature of the invention is the provision of a timing circuit common to a 10 plurality of switching units for counting off a time interval, following the taking of a unit into use by an operator, and in the event that a switching unit does not function completely within a prescribed period 15 for operating an alarm. More particularly, this feature relates to the provision of means for testing the timing leads extending from the common timing circuit to the several units for detecting such conditions 20 on the timing leads as would prevent the correct functioning of the timing circuit with relation to the switching units.

Other and further features contemplated 25 in the present invention will be obvious from a consideration of the description given hereinafter and also from the appended claims.

Referring to the drawings, Figs. 1 to 14, when taken in the order shown in Fig. 15, 30 disclose so much of a telephone system embodying the principles of this invention as is necessary to a comprehensive understanding thereof.

Fig. 1 shows one of a plurality of toll 35 operators' positions in a toll switching office of the exchange, provided with cord circuits for extending incoming toll calls over interoffice trunks outgoing to the distant manual offices. One of these trunks 40 is also illustrated in this figure. In addition a toll district selector is also shown as having access to the trunk circuit, this toll district being under the direct control of a distant toll point.

Figs. 2, 3, 4 and 5 show the switches 45 which constitute one of a plurality of switching units. Figs. 2 and 3 illustrate two of a series of trunk selector switches for selecting idle trunks outgoing to a particular manual office. Fig. 4 shows a sender 50 selector switch having access to a group of common register senders. Fig. 5 shows an operator's position selecting mechanism which consists of a plurality of separate position selector switches, two of these 55 switches being shown in detail.

To the right of the right-hand broken line in Fig. 6, there is shown an operator's 60 position provided with office keys and a series of sender control keys. Between the two vertical broken lines another operator's position belonging to the same group of positions as the one shown at the right of the figure is also schematically illustrated. To the extreme left of this figure

is shown a third operator's position which is position No. 1 of the fifth group. Fig. 7 shows a set of indicating lamps located at the operator's position illustrated at the right in Fig. 6, the function of which is to give the operator a visual identification of the selected trunks at her position. Fig. 8 shows a starting and an allotting mechanism common to the entire group of switching units individual to the group of trunks 70 outgoing to the manual office illustrated. 75

Figs. 9, 10, 11 and 12 show one of a plurality of register senders located in the toll office and common to all operators' positions for controlling the setting of call indicators in the distant manual offices. Figs. 9 and 10, taken together, show a register control switch, and its associated circuits. Fig. 10 also in the right portion thereof shows a call indicator impulse switch for 80 transmitting call indicator code impulses. Figs. 11 and 12 show sets of relay registers upon which the designations of called lines are recorded. Fig. 13 shows a timing circuit common to a plurality of switching 85 units for operating an alarm in the event that a switching unit fails to function properly within a predetermined period, together with testing circuits for testing the timing leads extending from the common 90 timing circuit to the several switching units to which it is common.

Fig. 14 shows the incoming end of the trunk circuit illustrated in Fig. 1, terminating at a manual operator's position in a 100 manual office of an exchange, together with a relay call indicator illustrated in the broken line rectangle in the lower portion of the figure. At the right of the figure a line of a subscriber terminating in the manual office is disclosed. 105

General description of apparatus and operation.

The trunk selector switches 200 and 300, the sender selector 400, the position selectors 500 and 510, the allotter switch 800, and the register control switch 1000 shown in Fig. 10, are all of the rotary single motion step-by-step type driven by stepping magnets from terminal to terminal and so arranged that the brushes are moved forward to the next terminal upon deenergization of the stepping magnet. 110 115 120

In the system disclosed, connections are established by the operator in the manual toll office to any of a plurality of distant manual offices. For each manual office to which the operators in the toll office have 125 access there is provided a group of interconnecting trunk lines terminating at the manual office in calling plugs. At the toll office these trunks are multiplied so as to appear in jacks before each of the oper- 130

ators' positions. The operator responds to an incoming toll call in the usual manner and upon ascertaining the name of the wanted office and the number of the wanted line therein, she manipulates the necessary apparatus at her position which causes the automatic selection of an idle trunk outgoing to such office; the association of an idle register sender with her position and with the selected trunk, and the visual indication on indicator lamps of the identity of the selected trunk. She then sets up the number of the wanted line on a keyboard at her position and completes the connection by inserting the calling plug of her cord circuit into the jack of the indicated outgoing trunk. The manipulation of the operator's keyboard causes the desired designation to be registered upon the registers of the associated sender which thereafter serve to control the call indicator in the distant manual office to indicate the number of the wanted subscriber's line.

As above noted, there is a group of outgoing trunks from the toll office to each of the distant manual offices served. Only one of these distant offices 1450 illustrated in Fig. 14 of the drawing, and one of the trunks 117, 118 leading thereto have been shown herein. For the group of trunks leading to the manual office there is provided in the toll office a plurality of switching units, only one of which is shown in Figs. 2, 3, 4 and 5. While these switching units are individual to a single group of trunks outgoing to a single distant office, they are common to all register senders and are also common to all operators' positions in the toll office. Each of these switching units comprises a series of trunk selector switches, two of which are shown at 300 and 200, respectively.

Assuming that the group of trunks outgoing to the office in Fig. 14 is made up of 160 trunks, there will be provided in that case eight trunk selecting switches each having a capacity of twenty trunks. The switch 300 serves the first twenty trunks in the group, the switch 200 serves the second twenty trunks, and so on for the remaining six selector switches. The switch 300 comprises a stepping magnet 301 and a plurality of brushes 302, 303, 304, 305, 306 and 307, and their cooperating terminal banks. Similarly, the switch 200 consists of a stepping magnet 201 and brushes 202, 203, 204, 205, 206 and 207, and the corresponding terminal banks. The same is true of the succeeding selector switches not shown. The terminal banks with which the brushes 306 and 307 of the selector switch 300 cooperate, and the banks with which brushes 206 and 207 of switch 200 cooperate, and the corresponding banks of all succeeding switches in the series have their terminals multiplied, as illustrated, for a purpose

which will become obvious from the following description. Common to the entire series of trunk selector switches there is provided a steering or side switch 210 consisting of stepping magnet 221, brushes 222, 223, 224, 225, 226, and 227 and their cooperating terminal banks. The purpose of the side switch 210 is to determine the first one of the series of trunk selectors to be taken for use and to govern the circuit changes during the transition from one selector switch to the next. Provided all trunk selectors are in their normal positions when a switching unit is taken for use, the first one of the switches in the series, namely the switch 300, will be set in motion to hunt for an idle trunk in the first group of twenty. If all these trunks are busy the switch 300, having moved its brushes completely over their bank terminals, causes the advance of the side switch 210 to its next position where the second trunk selector in the series is then effective and operates to search for an idle trunk in the second group of twenty. This procedure continues until an idle trunk is finally found. The side switch 210 has no normal position but remains in the position corresponding to the trunk selector switch last taken for use so that when the unit is next operated, that particular selector switch in the series is set in motion to search for an idle trunk instead of commencing again at the beginning of the series.

In addition to the trunk selector switches, the switching unit also consists of a sender selector switch 400 comprising a stepping magnet 401, brushes 402, 403, 404, 405, 406 and 407 and their corresponding terminal banks.

Lastly, the switching unit includes, together with the trunk selectors and the sender selectors, a plurality of operator's position selector switches, two of which are shown at 500 and 510. The switch 500 comprises a stepping magnet 507, brushes 501, 502, 503, 504, 505 and 506 and their corresponding terminal banks, while the switch 510 similarly consists of a stepping magnet 517 together with brushes 511, 512, 513, 514, 515 and 516. In order to secure a better understanding of the purpose for dividing the position selecting mechanism up into a plurality of selector switches, each separate and distinct from the other, an explanation will first be given of the plan on which the operators' positions are grouped and divided.

Assume that the toll office has one hundred operators' positions, which is a greater number than a single position selector switch of the usual type can serve with the requisite speed and efficiency. Accordingly, the total number of one hundred operators' positions is divided into five different groups of twenty positions each, and

each of the switching units is provided with five position selector switches each having a capacity for twenty operators' positions. The position selector 500, for example, 5 serves the first group of twenty operators' positions in the office. The first and second of these positions in the first group of twenty are illustrated at 600 and 610. The next three succeeding position selector 10 switches, which are not shown in the drawing, serve the next three groups of twenty operators' positions. Finally, the last or fifth position selector switch 510 serves the fifth group of twenty operators' positions, 15 the first position of which is schematically shown at 620 of Fig. 6. The function of the position selector switch 500 of the switching unit shown is to associate any one of the twenty positions with the register sender 20 selected by the switch 400 of the same unit and to associate the trunk indicating mechanism in Fig. 7 at the operator's position with the controlling devices pertaining to the trunk selecting switches of the same 25 unit, and which are shown in Fig. 3. Likewise, this is the function of the remaining four position selector switches of this switching unit with respect to the succeeding four groups of twenty operators' positions. 30

Since there are a plurality of switching units individual to each outgoing group of trunks, there are, not shown, a number of switching units equivalent and identical to the one shown in Figs. 2, 3, 4 and 5. The trunk selector switches, similar to 300 and 200 of each of these remaining units, have access to the same outgoing trunks; the sender selectors, similar to switch 400, have access to the same common senders, and the position selector switches 500, 510, etc., all have access to the same corresponding groups of operators' positions. Where these switching units are all equivalent to one another and may be taken for use by any one of the operators in the exchange, an allotting device is employed for allotting an idle switching unit for the use of any operator and for preventing more than one switching 45 unit being taken for use at the same time. The allotter for this purpose is shown in the form of the switch 800 in Fig. 8. Switch 800 consists of a stepping magnet 801, brushes 802, 803, 804, 805, 806 and 807 and 50 their corresponding terminal banks. The brush 807 and its terminal bank pertain to the first position selector switch 500 of each of the several equivalent switching units. The brush 803 and its terminal bank pertain to the fifth or last position selector switch 510 of each of the switching units. Similarly, the intermediate brushes 806, 55 805 and 804 pertain, respectively, to the three intermediate position selectors of each switching unit belonging to the outgoing 60

group of trunks leading to the office 1450.

The balancing coil 812, together with the polarized relay 814, acts to initiate the operation of the allotted switching unit under the control of any operator in the first group of operators. The balancing coil 813 and polarized relay 815 act to initiate the movement of the allotted switching unit under the control of any operator in the last or fifth group of operators. Likewise, three intermediate balancing coils are provided (not shown), and serve, respectively, to start the allotted switching units under the control of operators in the three respective intermediate groups. The five balancing coils are individual, respectively, to the five position selector switches of each switching unit. For example, the coil 812 is individual to the position selector 500 having access to the first group of twenty operators' positions. The coil 813 is individual to the fifth position selector switch 510 having access to the fifth group of twenty operators' positions. The same is true of the remaining balancing coils and position selector switches. 85

The register sender, shown in Figs. 9, 10, 11 and 12, comprises a plurality of groups of registering relays, a group for each digit to be recorded, which through the progressive operation of the switch 1000 are placed under the control of the operator's keyboard, and an impulse switch of the sequence switch type which in accordance with well known practice is arranged to send, during two revolutions thereof, series of impulses the character of which is determined by the several groups of register relays. These series of impulses are transmitted to the manual terminating office for causing the call indicator therein to record the desired line designation. 95

Each of the several operators' positions is equipped with a plurality of keys individual to the different outlying manual offices to which connection may be extended from the toll office. The keys 601, 621 and 627 at each of the three positions shown in the drawing, are individual to the manual office 1450. The manipulation of one of these keys by the operator at the corresponding position initiates the movement of the allotted switching unit individual to the group of trunks outgoing to that office. For every other office similar to the office 1450, served through the toll office illustrated in this disclosure, there will be at each operator's position an office key similar to those shown. The actuation of these keys will, in a similar manner, cause the movement of an allotted switching unit, similar to the one shown in Figs. 2, 3, 4 and 5, but individual to the particular distant office represented by the key depressed. 110 115 120 125

Two types of toll points are disclosed in 130

Fig. 1, one shown in the upper left portion of the figure comprising a toll switching operator's position provided with a plurality of toll cords, only one being shown, and the associated key indicator mechanism shown in Figs. 2 to 13 inclusive. While this toll cord has been shown, for simplicity of disclosure, as having access directly to a calling line for answering calls initiated thereby, it would in practice be associated with the usual "A" and recording operators' positions and calls incoming from toll points would be handled in accordance with standard toll practice.

The toll line switch 174 and the toll district selector 175, shown in the lower left portion of Fig. 1, are employed for establishing toll connections from other distant toll points and may be of the general type disclosed in the application of W. C. Jordon Serial No. 680,807, filed Dec. 15, 1923. Since the specific construction of these switches and the manner in which they are controlled by dial pulses from the distant toll points to select a trunk extending to the desired office of the exchanges are immaterial to an understanding of the invention, a detailed disclosure thereof is unnecessary herein.

The call indicator trunk shown in Fig. 14 and the call indicator associated therewith are of substantially the same type as disclosed in the Patent No. 1,464,084, issued to A. E. Lundell and E. H. Clark, August 7, 1923. The call indicator has been indicated diagrammatically in the small rectangle in the lower left portion of the figure, and reference to the aforementioned patent may be had for a full disclosure thereof.

40 Detailed description of operation.

A general description having been given of the system and its purposes, a detailed explanation will now be made with respect to the establishment of a telephone connection. To this end it may be assumed that the subscriber of line 125 at a distant toll point desires to converse with the subscriber of line 1475 in the manual office 1450. The calling subscriber upon initiating a call becomes connected with the toll switching office in the well known manner. The operator ascertaining the number and office of the calling line and the office and number of the desired line over an order wire connection or in any well known manner, actuates the office key 601 of her position which bears the name of the office 1450 in which the wanted line terminates. The depression of key 601 completes a circuit from ground through the outer back contact of relay 611, left contact of key 601, right winding of relay 602, right winding of relay 603, contact of relay 613 to battery. Relays 602 and 603 operate

65 in this circuit and close a holding circuit

for themselves as follows: battery through the contact of relay 613, right windings of relays 603 and 602, inner left contact of relay 602, inner back contact of relay 612, inner left front contact of relay 603 to ground. The depression of key 601 also closes a circuit from battery, through the winding of relay 609, inner back contact of relay 611, right contact of key 601 to ground. Relay 609 operates and closes a circuit from battery through its winding and the winding of relay 611 in series, front contact of relay 609, outer left contact of relay 603 to ground. Relay 611, which is shunted as long as key 601 is held actuated, operates in series with relay 609 over the circuit just traced at the instant the operator releases the key 601. The operation of relay 603 closes a circuit from battery through the right contact of said relay, back contact of relay 605, lamp 607, outer back contact of relay 606 to ground. The lamp 607 lights and remains lighted under the observance of the operator until an idle register sender has become associated with her position.

Immediately that relay 602 is energized a circuit is closed from battery through resistance 614, outer contact of relay 612, outer left contact of relay 602, conductor 821, thence to a point between the lower winding of the balancing coil 812 and the polarized relay 814. The flow of current to ground through the coil 812 and through the winding of the polarized relay 814 is in such a direction as to cause said relay to attract its armature. Relay 814 closes a circuit from battery through its contact, winding of relay 809, normal contacts of said relay, contact of relay 811 to ground. Relay 809 operates and closes a locking circuit for itself through its inner left contact to ground. Relay 809, at its outer left contact, closes an energizing circuit for relay 811. Relay 811 attracts its armature and removes ground from conductor 823 thereby preventing the operation of another relay similar to relays 809 and 810 until the allotted switching unit has been started and another one allotted in its stead. Relay 809, on operating, closes a circuit from ground through the contact of relay 808, conductor 824, right front contact of relay 809, brush 807, conductor 820, leading to the switching unit which is allotted by the allotter switch 800 when standing in the position shown, winding of relay 508 to battery. Relay 508 operates and closes a locking circuit for itself from battery through its winding and inner left contact to ground at the contact of relay 521. Relay 508 completes a circuit from ground through its outer right front contacts, conductor 535, right back contact of relay 520, and thence in parallel through the winding of relay 519 to battery and over conductor 536 through the left winding of

relay 408 to battery. Relay 519 operates closing a circuit for relay 509 from ground on conductor 535, right back contact of relay 520, inner front contact of relay 519, left 5 normal contacts of relay 509 to battery through the winding of relay 509. Relay 509 upon energizing locks over its left front contact to ground on conductor 535 and at its right front contact closes an obvious circuit 10 for relay 520 and a locking circuit for relay 519. This locking circuit extends from battery through the winding and inner left contact of relay 519, conductor 530, outer left contact of relay 409, conductor 423, outer 15 left back contact of relay 525 to ground at the right contact of relay 509. Relay 408 also energizes and locks in a circuit from battery through its right winding, conductor 537 to ground through the right contact of 20 relay 509.

Relay 519 performs no other useful function at this time. Relay 520 operates and applies a ground potential to the conductor 816 which serves to render the switching 25 unit busy to the allotter switch 800 and also initiates the movement of the allotter to select and allot the next idle switching unit for use. The operation of the allotter will be considered at a later point in the description. Relay 509 also closes a circuit from battery through the left winding of relay 522, normal contacts at the inner left armature of relay 523, left front contact of relay 509 to ground on conductor 535. Relay 522 30 becomes energized and locks in a circuit from battery through its right winding and right front contact, front contacts of the inner right armature of relay 508, brush 501 and its normal position terminal, outer right 35 front contact of relay 508 to ground. Relay 522 also closes a circuit from battery through the right winding of relay 523, left contact of relay 522, contact of relay 521 to ground. Relay 523 operates and locks in a circuit 40 from battery through its left winding and inner left front contact, left front contact of relay 509 to ground on conductor 535. With relays 522 and 523 operated a circuit is closed for the stepping magnet 507 of the 45 position selecting switch 500, which has access to the first group of twenty operators' positions containing position No. 2, shown at 610, at which the depression of key 601 has initiated the movement of the switching 50 unit. The circuit for the magnet 507 may be traced from battery through the winding and contact of said magnet, inner right front contact of relay 508, right contact of relay 523, left front contacts of relay 522, contact of relay 521 to ground. Magnet 507 55 interrupts its own circuit and advances the brushes 501, 502, 503, 504, 505 and 506 from position to position in the direction indicated by the arrows, the test brush 501 testing the condition of successive operators' 60

positions. The terminals with which brush 501 cooperates, representing non-calling positions, will present a ground potential to the brush 501, this ground potential serving to maintain the holding circuit of relay 522, 70 above traced, closed. When, however, the brush 501 reaches the second position terminal representing the second operator's position 610, no ground potential will be found thereon due to the energized condition of relay 602. Hence the circuit of relay 522 is opened and this relay becomes deenergized, opening, in turn the operating circuit of the stepping magnet 507 whereby the switch 500 comes to rest. Immediately that relay 522 75 releases its armatures a circuit is closed from battery, contact of relay 613, through the right winding of relay 612, right front contact of relay 602, conductor 632, brush 501, front contacts of the inner right armature of relay 508, right back contact of relay 522, winding of relay 524, outer front contact of relay 519, outer left contact of relay 523 to ground on conductor 535. Relays 612 and 524 become energized. 80 Relay 612 closes a holding circuit for itself from battery through its left winding and inner left front contact to ground at the inner left contact of relay 603 and also opens the previously traced locking circuit of relays 602 and 603, but these 85 relays remain energized in a substitute locking circuit traceable from battery through the contact of relay 613, left windings of relays 603 and 602 in series, front contacts at the right armature of relay 602, conductor 632, and thence to ground through the winding of relay 524, as above traced. Relay 612, at its outer left contact, disconnects battery from the conductor 821 and the balancing coil 812. 90

Relay 524, which energizes in series with relay 612, completes a circuit from battery through the winding of relay 526, outer right contact of relay 410, conductor 541, contact of relay 524, conductors 542 and 423, outer left back contact of relay 525 to ground on conductor 537. Relay 526 operates and closes a circuit from battery through its winding and the winding of relay 525, right contact of relay 526, conductor 537 to ground. Relay 525, however, can not operate in this circuit since it is shunted by the direct circuit traced from battery through the winding of relay 526 and the contact of relay 524 to ground. With relay 526 operated a circuit is established from battery through the right back contact of relay 525, left front contact of relay 526, winding of relay 527 inner front contact of relay 519, conductor 530, thence to ground as traced on conductor 537. The operation of relay 527 serves as an indication that the operator's position has been found, 100 105 110 115 120 125 130

The selected operator's position is maintained nonselectable to other position switches by the application of ground potential to the test terminals of all switches, similar to 500, with which the brushes 501 cooperate. It will be understood, of course, that the terminals of the position selector switches are multiplied to the terminals in corresponding switches of other units. The circuit for the application of this ground potential to the multiple test terminals of selector 500 and its corresponding selectors in other switching units may be traced from ground through the outer left contact of relay 523, outer left contact of relay 519, winding of relay 524, right back contact of relay 522, front contacts at the inner right armature of relay 508, brush 501, and thence to the multiple terminals representing the operator's position selected. The resistance of relay 524 is comparatively low so that the potential on the test terminals acts to render the position nonselectable to other switches.

25 The relay 408, which energizes at the time the office key 601 is depressed, serves to close an obvious circuit for relay 417 for initiating the counting of time as will be described hereinafter and serves to initiate the movement of the sender selector switch 400 to select an idle register sender. Upon the operation of relay 408 a circuit is closed from battery through the right winding of relay 412, normal contacts at the left armature of relay 413, conductor 431, outer left front contact of relay 408 to ground. Relay 412 energizes and closes a locking circuit for itself as follows, provided the register sender, upon the terminals of which the brushes of the selector 400 are now standing, is busy: battery through the left winding and left front contact of relay 412, conductor 419, test brush 407, test terminal of the busy sender, and thence to ground. Relay 412, on remaining energized, closes a circuit from battery through the right winding of relay 413, inner right contact of relay 412 to ground on conductor 431. Relay 413 operates and closes a circuit for itself from battery through its left winding and left front contact, to ground on conductor 431, and opens the energizing circuit through the right winding of relay 412 whereby this latter relay is now dependent for its continued energization upon the test circuit through its left winding and the test brush 407. At its left front contact relay 413 also closes a circuit from ground on conductor 431 through the left winding of relay 414, relay 414 energizing. With relays 412 and 413 both energized a circuit is established from battery through the winding and contact of the stepping magnet 401, outer right contact of relay 412, left front contact of relay 413 to ground on conductor 431. Magnet 401 op-

erates to advance the brushes of the switch 400 forward to their next position terminals.

The magnet 401 interrupts its own circuit and continues to advance the brushes of the sender selector switch until the test brush 70 407 encounters a non-grounded terminal identifying an idle register sender. At the instant an idle sender is reached the holding circuit of relay 412 is opened and this relay becomes deenergized to open the stepping circuit of magnet 401. Relay 413, however, remains energized. When relay 412 becomes deenergized a circuit is closed from ground through the inner right contact of relay 413, thence in parallel through 80 the right contact and winding of relay 414 to ground and through the left back contact of relay 412, conductor 419, test brush 407 and the multiples of the test terminal upon which it is standing to mark the sender busy. Relay 412 at its outer right back contact establishes a circuit from battery through the winding of relay 426, outer right front contact of relay 413, outer right back contact of relay 412, left front contact of relay 413 to ground on conductor 431. Relay 426 operates and closes a circuit from battery through the winding of relay 900, right back contact of relay 901, conductor 925, brush 95 408, left contact of relay 426 to ground at the outer left back contact of relay 425. Relay 900 energizes for a purpose to be described hereinafter.

90 In parallel with the circuit of relay 426, relay 412 serves in conjunction with the relay 527, which is operated at this time provided the operator's position has been selected, to complete a circuit for the connecting relay 529. This circuit may be traced from battery through the winding of relay 529, outer right contact of relay 527, conductor 539, outer right front contact of relay 413, outer right back contact of relay 412, left front contact of relay 413, conductor 431, outer left contact of relay 408 to ground. Relay 529, at its armatures and contacts extends the three conductors 420, 421 and 422 from the selected register sender through the brushes 504, 505 and 506 to the operator's keyboard whereby the manipulation of these keys will serve to record the designation of the called line on the registers of the sender. At the time the sender is selected a circuit is closed from ground through the outer left contact of relay 603, inner left back contact of relay 603, winding of relay 605, inner left back contact of relay 604, brush 505, middle contact of relay 529, conductor 421, inner right back contact of relay 409, brush 405, conductor 915, outer right back contact of relay 902, brush 1004 of the control switch 1000 and its normal position terminal, conductor 1008, left winding of relay 1202, left winding of relay 1201, conductor 1209, inner right con- 105 110 115 120 125 130

tact of relay 300 to battery. Relay 605 operates in this circuit but its resistance is such that the relays 1202 and 1201 do not receive sufficient current to become energized. Relay 605 closes a holding circuit for itself from battery at the right contact of relay 603, through its contact and winding, and thence to ground, as traced, at the outer left contact of relay 603. Relay 605, at its front contact, also closes an obvious circuit for relay 604. Relay 604 connects the operator's keyboard, shown at the right of Fig. 6, to the three control conductors 420, 421 and 422. Relay 605 also at its back contact, opens the circuit of lamp 607 and causes the same to become extinguished which serves as an indication to the operation that a sender has been selected and is now in condition to receive the record of the called subscriber's line.

The operation of relay 408, which causes the movement of the sender selector switch 400, also serves to initiate the movement of a trunk selector switch for the purpose of selecting an idle trunk leading to the manual office 1450. It will be observed that all three switches, namely the operator's position selector, the sender selector, and the trunk selector are operated simultaneously. Assume that all trunk selector switches 300, 200, etc., are in their normal positions at the time the switching unit is taken for use. Accordingly, the side switch 210 will be standing with its brushes 222, 223, 224, 225, 226 and 227 upon the No. 3 terminals of the corresponding banks. Positions 3 to 10, inclusive, of the side switch represent, respectively, the eight trunk selector switches in order. Terminals 11 to 18 also represent, respectively, the series of eight trunk selector switches and accordingly these terminals are multiplied to terminals 3 to 10, as shown in the drawing. In this manner the side switch controls in a single revolution two successive operations of the entire series of eight trunk selector switches. With the first trunk selector 300 in its normal position and with the side switch 210 in position 3, the operation of relay 408 causes the closure of a circuit from battery through the left winding of relay 311, the left normal contact of relay 310, conductor 319 to ground at the inner left contact of relay 408. Relay 311 upon energizing closes an obvious circuit for relay 310, which locks over its left front contact to ground on conductor 319. Relay 311 locks over its right winding and right front contact, conductor 328, outer right front contact of relay 408, conductor 218, brush 224, conductor 233, to ground over brush 303 and its normal terminal. As soon as relay 310 energizes the initial energizing circuit of relay 311 is opened at the left contacts of relay 310, so that relay 311 depends for its continued energization on

the test circuit traced over brush 303. With relays 310 and 311 both energized, a circuit is established for magnet 301 extending from battery, winding and contact of magnet 301, conductor 231. No. 3 terminal 228 of switch 210, brush 223, conductor 216, inner left front contact of relay 311, inner right and left front contacts of relay 310 to ground on conductor 319. The stepping magnet 301 interrupts its own circuit and advances the brushes of the switch 300 to their No. 0 position terminals, which represent the first trunk in the first group of twenty. If the first trunk is busy a ground potential will exist upon the No. 0 test terminal and the stepping magnet 301 is again energized. Assume that all trunks of the first group of twenty are busy. This being the case the brushes of the selector switch 300 are stepped around until they reach their No. 20 terminals. When these terminals are reached a circuit is closed from battery through the winding of relay 229, brush 225, conductor 220, the No. 20 terminal 329, brush 307, conductor 326, next to the inner back contact of relay 528 to ground. A second circuit is also closed from ground at the innermost back contact of relay 528, conductor 327, brush 306, No. 20 terminal 331, conductor 320, brush 222, No. 3 terminal 230, conductor 214, to battery through the winding of magnet 301 for preventing the switch 300 from advancing to position No. 21 until the switch 210 has selected the switch 200. Relay 229 becomes energized and on attracting its right armature establishes a circuit from battery through the winding and contact of magnet 221, brush 225 and its No. 3 terminal, conductor 220, thence as traced to the next to inner back contact of relay 528 to ground. Magnet 221 becomes energized and interrupts its own circuit and advances the brushes 222, 223, 224, 225, etc., of the side switch 210 from their No. 3 to their No. 4 terminals, in which position they are shown in the drawing. As brush 222 disengages its No. 3 terminals the above traced circuit of magnet 301 is opened and this magnet becomes deenergized to advance the brushes of the first selector switch 300 to their No. 21 terminals, or to their normal position. The circuit of relay 229 is also opened, in turn opening the circuit of magnet 221.

Immediately that brush 223 encounters its No. 4 terminal a circuit is completed from battery through the winding and contact of stepping magnet 201, conductor 215, brush 223, conductor 216, and thence through the inner left front contact of relay 311, inner right and left front contacts of relay 310, conductor 319 to ground at the inner left contact of relay 408. Magnet 201 interrupts its own circuit and advances the brushes of the selector switch 200 on to

their No. 0 terminals testing the condition of the first of the second group of twenty trunks. Assuming that all trunks preceding the trunk No. 31 are busy, therefore the magnet 201 continues to advance the brushes until they reach the terminals of this idle trunk at which time no ground potential is found on the terminal engaged by test brush 203. Due to the absence of ground potential on the test terminal, the holding circuit through the right winding of relay 311 is opened and this relay now deenergizes, opening the operating circuit of magnet 201.

15 The relay 311 completes a circuit from ground on conductor 319, through the left front contact of relay 310, through the right back contact of relay 311, conductor 328, conductor 218, brush 224, conductor 217, brush 203, and thence to the multiple terminals of the selected trunk in all other trunk selector switches. In this manner the outgoing trunk 117, 118, which has just been selected by the selector switch 200, is rendered non-available to any other switch. Relay 311, furthermore, completes a circuit from ground through its outer left back contact, outer right front contact of relay 310 to battery through the winding of relay 427. Relay 427 energizes and at its left contact completes a circuit from ground through the inner right contact of relay 527 to battery through the winding of relay 528. Relay 528, the circuit of which it is to be noted depends upon the fact that the operator's position selector has found the position and the trunk selector has found an idle trunk, serves to extend certain control conductors through from the trunk selector switches to the indicating equipment at the operator's position. Relay 528 connects ground through its innermost front contact to conductor 330 for purposes to be later described.

45 *Operation of trunk indicating mechanism.*

The complete switching unit has thus been operated, an idle trunk selected, and an idle register chosen and associated with such trunk and also associated with the particular operator's position on which the movement of the switching unit was initiated. The next operation to be described is the indication on the lamps at the operator's position of the identity of the trunk that has been chosen in order that the operator may extend the connection over this trunk. Upon the operation of relay 528 a circuit was closed from ground through the right high resistance winding of relay 312, brush 227 and its No. 4 terminal, conductor 323, inner left back contact of relay 314, conductor 325, next to the outermost contact of relay 528, brush 503, conductor 701, right back contact of relay 702, left winding of sensitive relay 704, left winding of marginal relay 706 to battery. Relay 704 operates but due to the high resistance of the right winding of relay 312 the marginal relay 706 remains inert. Relay 704 locks in a circuit from battery through its right winding and right contact, conductor 720, inner left front contact of relay 603 to ground. At the same time a circuit is closed from ground through the left low resistance winding of relay 312, brush 226 and its No. 4 terminal, conductor 322, outer left back contact of relay 314, conductor 324, outermost contact of relay 528, brush 502, conductor 700, inner left back contact of relay 702, left winding of sensitive relay 703, left winding of marginal relay 705, conductor 722, right contact of relay 603 to battery. Due to the low resistance of the left winding of relay 312 both the sensitive relay 703 and the marginal relay 705 are energized. Relay 703 locks in a circuit from battery through its right winding and inner right contact to the grounded conductor 720, while relay 705 locks in a circuit from battery through its right winding and inner right contact, conductor 723 to ground at the outer left contact of relay 603. The relay 312 becomes energized in the circuit traced and completes an obvious circuit for the relay 313. Relay 313, on operating, closes a holding circuit from battery through its winding and right contact, conductor 330, to ground at the innermost front contact of relay 528. Upon the energization of either of the relays 703 or 704 a circuit is closed over the inner left contact of one or the other of these relays through the winding of relay 702 to battery. It may be observed that either relay 703 or relay 704, or both, will be operated for every position that the side switch 210 may take. In other words, regardless of the group of twenty trunks in which the idle trunk is selected, the combination of the marginal and sensitive relays operated due to the position of the side switch will always include one or the other or both of the relays 703 and 704. Consequently, relay 702 is always operated. This relay is constructed so as to be slow in attracting its armatures and also slow-to-release. As soon as relay 702 becomes energized it opens the circuit of relay 312 and this latter relay releases and closes a circuit from ground through its back contact, left contact of relay 313, winding of relay 314 to battery. Relay 314 operates and disconnects the control conductors 324 and 325 from the conductors 322 and 323 leading to the side switch and connects them instead to the conductors 326 and 327, which extend in multiple to the corresponding brushes of the trunk selector switches.

65 A circuit is now established from ground

- through the left winding of marginal relay 714, left winding of sensitive relay 715, inner right back contact of relay 719, inner left front contact of relay 702, conductor 700, and thence, as traced, to conductor 324, outer left front contact of relay 314, conductor 327, conductor 317, brush 206, terminal 232, conductor 316, conductor 332, right contact of relay 314, conductor 333, middle right contact of relay 310, conductor 531, left contact of relay 527 to battery. Since the circuit traced includes no high resistance, both relay 715 and marginal relay 714 are energized. These relays lock in circuits through their right windings to the conductors 720 and 723, respectively. Furthermore, a circuit is closed from ground through the left winding of sensitive relay 716, left back contact of relay 719, right front contact of relay 702, conductor 701, thence through the conductor 325, inner left front contact of relay 314, conductor 326, conductor 318, brush 207, terminal 233, conductor 315, left low resistance winding of relay 308, normal left contact of relay 309, conductor 332, right contact of relay 314, middle right contact of relay 310, thence over conductor 531 to battery. Relay 716 operates and locks through its right winding to the grounded conductor 720. Relay 308 also operates in this circuit and closes a circuit from battery through the outer left contact of relay 527, conductor 531, middle right contact of relay 311, right contact of relay 314, conductor 332, normal left contacts of relay 309, left contact of relay 308, winding of relay 309, conductor 330 to ground. Relay 309 attracts its armatures and closes a locking circuit for itself through its left armature and make-before-break contact, independent of the left armature and contact of relay 308. Relay 308 remains energized, temporarily, over a modified circuit which leads from ground, as above traced, over conductor 315, left winding of relay 308, left contact of said relay, left armature and front contact of relay 309, and thence to battery over conductor 332.
- Immediately that one or the other of the two relays 715, 716 is operated, an obvious circuit is established for the energization of relay 717. Relay 717, upon operating, closes a circuit for relay 718 and this latter relay, in turn, closes a circuit from battery through the winding of relay 719 contact of relay 718, and thence to ground at the inner left contact of either relays 715 or 716. Relay 719, upon operating, opens the circuit of relay 308, permitting the same to release its armatures. A circuit is then closed from ground through the right contact of relay 309, right contact of relay 308, conductor 326, inner left front contact of relay 314, conductor 325, next to the outermost contact of relay 528, brush 503, conductor 701, right front contact of relay 702, left front contact of relay 719, through the windings of relays 708 and 709 in parallel, to battery. Relays 708 and 709 become energized in this circuit.
- With the lamp controlling relays operated in the combination above described, the proper lamps are selected and illuminated for indicating the identity of the selected trunk 117, 118 to the operator. Since the number of the selected trunk is 31, it is necessary to illuminate the No. 3 tens lamp 710 and the No. 1 units lamp 711. The circuit for lamp 710 may be traced from battery through the right front contact of relay 709, filament of lamp 710, outer left contact of relay 705, outer left front contact of relay 704, outer right contact of relay 719 to ground. The circuit for lamp 711 may be followed from battery through the inner left back contact of relay 713, filament of lamp 711, outer left contact of relay 714, outer left front contact of relay 716 to ground at the outer right contact of relay 719. The operator, observing the number 31 displayed on the indicating lamps, knows that trunk No. 31 is to be used in the extension of the call.
- Positioning of the register sender from operator's keyboard.*
- As soon as the operator observes the extinguishment of sender lamp 607 she proceeds to depress the non-locking keys at her position representing the number of the wanted subscriber's line which was communicated to her by the recording operator. Assuming the called number to be 1647, the operator actuates the No. 1 key 615, the No. 6 key 616, the No. 4 key 617, and the No. 7 key 618 in succession. The depression of key 617 completes a circuit from ground over the inner left contact of relay 603, conductor 720, resistance 619, right contact of key 615, inner left front contact of relay 604, brush 505, middle contact of relay 529, conductor 421, inner right back contact of relay 409, brush 405, conductor 915, outer right back contact of relay 902, brush 1004 and its normal position terminal, conductor 1003, left winding of relay 1202, left winding of relay 1201, conductor 1209 to battery at the inner right contact of relay 900. Relay 1201 operates in this circuit but due to the inclusion of resistance 619 the marginal relay 1202 remains inert. Relay 1201 locks in a circuit from ground through its right contact and right winding to battery on conductor 1209. Another circuit is completed from ground on conductor 720, the left contact of key 615, outer right front contact of relay 604, brush 504, outermost right contact of relay 529, conductor 420, brush 404, winding of relay 904, brush 1002 and its normal pos-

tion terminal, conductor 1009, right winding of relay 1200 to battery on conductor 1209. Since no resistance is included in this circuit the marginal register relay 1200 operates and locks through its inner left contact and both windings to battery on conductor 1209. With relays 1200 and 1201 both energized a circuit is established from ground over right contacts of these relays through the right winding of relay 1204 to battery on conductor 1209. Relay 1204 energizes. Relay 904, which also becomes energized, completes a circuit from ground, left back contact of relay 902, through its right front contact, outer left back contact of relay 906, and winding of stepping magnet 1001 to battery. Relay 907, which is energized in parallel with the stepping magnet, over the contact 908 of relay 906 and the contact of magnet 1001, closes a locking circuit for itself including the contact of magnet 1001 and also closes a holding circuit for magnet 1001 independent of the contact of relay 904. The magnet 1001 becomes energized and when its armature is fully attracted the circuit of relay 907 is opened and this relay becomes deenergized to in turn open the circuit closed thereby for magnet 1001. Magnet 1001 deenergizes as soon as relay 904 deenergizes upon the release of key 615 and advances the brushes of the register control switch forward one step to their No. 1 terminals. Register relays 1200, 1201 and 1204 are now operated.

Immediately that the register control switch reaches position 1 a circuit is closed from battery through the winding of relay 901, conductor 909, brush 1007 to ground. Relay 901 operates and closes a circuit from ground through the inner left contact of relay 900, right front contacts of relay 901 and thence in parallel through the winding of relay 900 to battery, and over conductor 910, brush 1006, conductor 911 to battery through relay 912. Relay 901 at its left contact places ground potential on the hunting lead 424. Relay 912 closes a circuit from ground over conductor 913, brush 402, right contact of relay 426, right back contact of relay 432, to battery through relay 425. Relay 425 thereupon locks through the winding of relay 432 and the inner left contact of relay 425 to ground at the right back contact of relay 415. Relay 432 being shunted, does not energize at this time. Relay 425 performs no function at this time unless a wipe-out is attempted.

When the operator depresses No. 6 key 616, a circuit is closed from ground over conductor 720, resistance 619, right contact of key 616, inner left front contact of relay 604, thence, as above traced, over conductor 421 to conductor 915 brush 1004 and its first position terminal, conductor 1010, left winding of relay 1212, left winding of relay 1211

to battery on conductor 1209. Relay 1211 operates and locks through its right winding but the relay 1212, being marginal, remains inactive. Another circuit is closed from ground over conductor 720, left contact of key 616, inner right front contact of relay 604, thence over conductor 422, brush 406, winding of relay 905, brush 1002, conductor 1011, right winding of relay 1210 to battery on conductor 1209. Relay 1210 operates and locks through its inner left contact and both windings. Relay 1205 also operates in an obvious circuit through the inner right contact of relay 1210. Relay 905 also energizes and causes the advance of the register control switch in the manner above described from position No. 1 to position No. 2. Relay 905, in addition, closes a circuit from ground through its left contact, brush 1003, conductor 1012, left winding of relay 1213 to battery on conductor 1209. Relay 1213 operates and locks through its right winding and inner right contact. Register relays 1205, 1210, 1211 and 1213 have now been operated.

Upon the depression of key 617 a circuit is closed from ground over conductor 720, right contact of said key, thence over conductor 421, as above traced, conductor 915, brush 1004, terminal No. 2, conductor 1013, left winding of relay 1102, left winding of relay 1101, conductor 1104, outer right contact of relay 900 to battery. Relays 1101 and 1102 operate and lock through their right windings. Another circuit is closed from ground over conductor 720, resistance 626, left contacts of key 617, thence, as above traced, over conductor 420, winding of relay 904, brush 1002, conductor 1014, right winding of relay 1100, conductor 1104 to battery. Relay 904 operates but relay 1100, being marginal, remains inactive. In the manner above explained the relay 904 causes the advance of the register control switch to its No. 3 position. Register relays 1101 and 1102 are now operated.

Upon the actuation of key 618 a circuit is established from ground over conductor 720, the left contacts of said key, thence over conductor 422, the winding of relay 905, brush 1002, conductor 1015, right winding of relay 1110, conductor 1104 to battery. Relay 1110 operates and locks through both of its windings. Relay 905 operates and closes a circuit through its left contact, conductor 935, brush 1003, conductor 1016, left winding of relay 1113, conductor 1104 to battery. Relay 1113 operates and locks through its right winding and right contact. Relay 905 also causes the advance of the register control switch from position 3 to position 4. Register relays 1110 and 1113 are now operated.

As the brush 1006 of the control switch leaves its No. 3 terminal the previously

traced circuit of relay 912 is opened and this relay deenergizes to remove the shunt from around the winding of relay 432. Relay 432 energizes in the locking circuit 5 of relay 425, preparing circuits which are effective if only four digits are to be registered and the operator plugs into the jack of trunk 117, 118 following the registration of the fourth numerical digit. It has 10 been assumed, however, that a station's letter W is to be registered. The operator before plugging into the jack of the indicated trunk therefore operates key 622. With 15 the control switch 1000 in position 4 a circuit is thereupon completed from ground at the inner left contact of relay 603, conductor 720, left contact of key 622, outer right contact of relay 604, thence as previously traced through the winding of relay 20 904, brush 1002, conductor 1017, right winding of marginal relay 1120 to battery on conductor 1104. Relay 1120 energizes and locks over its inner left contact and both 25 windings to battery on conductor 1104. Relay 904 also energizes at this time causing 30 the advance of the control switch as previously described from position No. 4 to position No. 5. Register relay 1120 is now operated.

With the control switch in either positions 4 or 5 the circuit of relay 916 is completed for extending conductors 913 and 925 to 35 cams of the impulse switch 1020 preparatory to the transmission of impulses for transferring the registrations from the relay registers of Figs. 11 and 12 to the call indicator of the selected manual office 1450. The circuit of relay 916 may be traced from battery, winding of relay 916, conductor 40 917, brush 1006, conductor 910, right front contact of relay 901 to ground at the inner left contact of relay 900. A circuit is also closed at this time through the left winding of relay 902, brush 1005, inner left 45 back contact of relay 906, conductor 909 to ground at brush 1007.

Extension of connection to terminating office.

The operator having completed the registration of the desired line number inserts the plug 106 of her cord circuit in the jack 50 107 of the trunk indicated by the lighted trunk indicating lamps whereupon a circuit is completed from battery through the relay 100, sleeve of plug 106, sleeve of jack 107, winding of relay 108 to ground. Relays 100 and 108 attract their armatures. Relay 108 at its inner left contact connects ground to the conductor 130 for marking 55 the selected trunk busy to other key indicator links which may attempt to make connection therewith to hold the trunk non-selectable after relay 310 has become de-

energized and removed the temporary busy ground potential. Ground potential is also connected over this contact and through the innermost left back contact of relay 110 to the multiples of test terminal 111 appearing 70 in the banks of toll districts, such as 175, for marking the selected trunk busy to all districts having access thereto. Upon the insertion of the plug 106 in the jack 107, a circuit is also established for relay 75 109, which may be traced from battery, through the winding of relay 109, the innermost lower back contact of relay 119, tip contacts of jack 107 and plug 106, winding of relay 120, contact of relay 100, ring 80 contacts of plug 106 and jack 107 to ground at the upper back contact of relay 119. The supervisory relay 120 energizes in this circuit and causes the illumination of lamp 121 in an obvious manner. Relay 109 upon 85 energizing establishes a circuit for relay 112 which may be traced from ground, inner left contact of relay 108, winding of relay 112, right normal contacts of relay 112, right contact of relay 109, outer left 90 contact of relay 108, right contact of relay 110, conductor 131, brush 202, conductor 208, right contact of relay 427, winding of relay 428, left contact of relay 432, right normal contacts of relay 429 to battery at 95 the left contact of relay 415. Relay 112 being marginal, does not energize in this circuit, but relay 428 energizes and closes a circuit for relay 409. Relay 409 upon 100 energizing, opens at its outer left normal contact the holding circuit of relay 519 and transfers the shunt circuit around the winding of relay 525 from the control of relay 524 to its own contact so that the shunting of relay 525 is thereafter dependent upon 105 the continued energization of relay 409.

Relay 519 upon deenergizing opens at its inner left front contact the circuit extending through the winding of relay 527 which thereupon opens the circuits of relays 528 and 529, and the locking circuit of relays 308 and 309. These relays thereupon deenergize. At its outer left back contact, relay 519 closes a circuit for relay 522 which may be traced through the left winding of relay 522, the outer left back contact of relay 519, the outer left front contact of relay 523, the left front contact of relay 509 to ground at the outer right contact of relay 508. Relay 522 energizes and at its 110 right back contact opens the previously traced circuit extending through the windings of relays 524, 602 and 603.

Relay 603 opens the circuits of relays 604, 605, 609, 611, 612, and of all energized 125 sensitive and marginal relays shown in Fig. 7. Relay 602 completes a circuit from ground through its normal right contact, conductor 632, brush 501, front contacts at the inner right armature of relay 508, right 130

front contact and right winding of relay 522 to battery for holding relay 522 energized. Relay 522 closes a circuit from battery through the winding of stepping magnet 507, contact of said magnet, inner right front contact of relay 508, right contact of relay 523, left contacts of relays 522, contact of relay 521 to ground. Magnet 507 interrupts its own circuit and advances the brushes of the position selector 500 from terminal to terminal. The relay 522 is maintained energized in each position of the switch 500 by ground potential on the terminal with which brush 501 cooperates extended from the normal right-hand contact of relays, similar to 602, 622 and 628, at non-calling operators' positions. When the switch 500 reaches the next to its normal position a circuit is closed from battery through the right winding of relay 522, right front contact of said relay, front contacts at the inner right armature of relay 508, brush 501, conductor 540, winding of relay 521 to ground. Relay 521 opens the holding circuit of relay 508, which relay becomes deenergized and opens the circuit of relay 509 and in turn the circuit of relay 520. Relay 520, on deenergizing, shunts relay 521 which deenergizes, and completes a circuit from battery through the winding and contact of magnet 507, inner right back contact of relay 508, brush 501, conductor 540, outer left back contact of relay 520 to ground. Stepping magnet 507 interrupts its own circuit once more and advances the brushes of the switch 500 to their normal position terminals. Upon the deenergization of relay 509, relays 522 and 523 release their armatures. The position selector switch 610 and all equipment at the operator's position 610 has thus been restored to its normal condition.

With relays 409 and 916 energized, a fundamental circuit is established from the register sender to the selected trunk circuit which may be traced from battery, through the left winding of relay 1400, the left normal contact of relay 1401, upper left winding of repeating coil 1402, upper back contact of relay 1403, conductors 117 and 128, brush 204, conductor 209, compensating resistance 334, conductor 335, inner left contact of relay 409, right contact of relay 426, brush 402, conductor 913, left front contact of relay 916, outer left back contact of relay 920, winding of relay 918, left contact of cam 1018, conductor 1019, left normal contact of relay 1206, conductor 1215, right front contact of relay 916, conductor 925, brush 403, left contact of relay 426, outer right contact of relay 409, conductor 211, brush 205, conductors 129 and 118, middle back contact of relay 1403, lower left winding of repeating coil 1402, right back contact of relay 1401 to ground through the right winding of relay 1400. Relays 1400 and 918 energize in this circuit, relay 918 closing an obvious circuit for relay 919 which in turn at its left contact establishes a holding circuit for relay 902 and at its right contact establishes obvious circuits for relays 921 and 922. Relay 902 upon energizing, locks over its inner right hand contact to ground at the inner left contact of relay 900, and at its left back contact removes ground from the armature contacts of relays 904 and 905 so that further depression of keys at the operator's keyboard will have no effect. Relay 921 upon energizing locks over its inner contact, conductor 1022, upper left contact of cam 1021, conductor 1023 to ground at the left contact of relay 901. This locking ground also locks relay 922. Thus both relays 921 and 922 are maintained energized until sequence switch 1020 leaves position 16 and opens the upper left contact of cam 1021 during its first revolution. Relay 922 upon energizing, prepares to connect the fundamental circuit conductors 913 and 925 to cams of the impulse sequence switch 1020 following the subsequent energizing of relay 920.

At the call indicator position, relay 1400 upon energizing, establishes a circuit for relay 1404 extending through the left back contact of relay 1411 to ground at the contact of relay 1400. Relay 1404 at its inner right contact establishes a circuit for the assignment lamp 1405 extending to battery at the inner right back contact of relay 1409 if the plug 1414 is down and to battery through the outer right front contact of relay 1404 if the plug 1414 is up at the time. Relay 1404 at its left contact, prepares a circuit for the assignment relay 1407. The manual terminating operator upon noting the illumination of lamp 1405 depresses the display key 1406 establishing a circuit for relay 1407 which may be traced in part from the relay call indicator 1429 through the upper contact of key 1406, the left contact of relay 1404, the right winding of relay 1407, conductor 1408, outer right contact of relay 1409, conductor 1410, to the call indicator. Relay 1407 energizes in this circuit and locks from ground over its inner left contact through both of its windings thence over conductor 1408 to battery at the call indicator. Upon the energization of relay 1407, a circuit is established from battery, through the winding of relay 1403, the outer left contact of relay 1407 to ground at the call indicator for associating the conductors 117 and 118 of the trunk circuit with the call indicator. Relay 1403 at its lowermost front contact, also establishes an obvious circuit for relay 1411, which at its left back contact opens the circuit of relay 1404 and at its left front contact locks to ground at the contact of relay 1400. With relay 1404

- deenergized, and relay 1407 energized the circuit of lamp 1405 is disconnected from direct ground at the inner right front contact of relay 1404, and connected through the inner right back contact of relay 1404 and the right front contact of relay 1407 to interrupted ground for the purpose of flashing the lamp 1405 during the setting of the call indicator.
- 10 Relay 1403 upon energizing also opens the previously traced circuit of relay 1400, but due to the energizing of relay 1411 a new local circuit is established for relay 1400 before it has time to retract its armature. This circuit extends through the windings of relay 1400 and the front contacts of relay 1401, relay 1401 becoming energized upon the energization of relay 1411 over a circuit extending from battery through its right winding and its innermost right contact to ground at the left back contact of relay 1409.
- 15 When the previously traced circuit through the windings of relay 1400 and relay 918 is opened, relay 918 deenergizes opening the circuit of relay 919 which in turn deenergizes and at its right front contact, opens the initial energizing circuit of the relays 921 and 922 and at its right back contact closes a circuit over the next to inner contact of relay 921 to battery, through the winding of relay 920. Relay 920 energizes and locks over its right contact, the upper left and lower right contacts of cam 1024, conductor 1025 to ground at the middle left front contact of relay 920. At its outer left and innermost left contacts, relay 920 completes the connection of conductors 913 and 925 of the fundamental circuit through contacts of relay 922 to cams of the impulse sequence switch 1020. In addition, relay 920 establishes a circuit extending from ground at its middle left front contact, the outer right front contact of relay 902, conductor 915, brush 405, the inner right front contact of relay 409 to battery through the winding of relay 429. Relay 429 energizes and establishes a locking circuit for itself extending from battery through its own winding, the winding of relay 430, the inner left contact of relay 429 to ground at the outer left front contact of relay 425. Relay 430, however, being shunted does not energize in this locking circuit. Relay 429 at its right normal contacts opens the circuit previously traced through the windings of relays 428 and 112 and connects direct battery to the winding of relay 112 over a circuit which may be traced as previously described through the winding of relay 112 thence to the right front contact of relay 427, the left back contact of relay 430, the right front contact of relay 429, to battery at the left contact of relay 415. Relay 112 of the trunk circuit now energizes opening its own circuit at its

right contact and locking itself in a circuit from ground over its innermost left front contact through its winding and to battery over its right front contact. When relay 112 energizes, ground is applied over its inner left contact and the inner left back contact of relay 110 to multiples of terminal 111 and over conductor 130 to mark the trunk busy to all switches having access thereto. Following the release of relay 428, 70 when its circuit is opened by relay 429, the initial energizing circuit of relay 409 is opened but the latter relay is maintained energized over the outer right back contact of relay 430, the right front contact of relay 429 to battery over the left contact of relay 415.

At the register sender upon the energization of relay 920, a starting circuit for sequence switch 1020 is closed extending from battery through the magnet winding of switch 1020, the upper left contact of cam 1026, conductor 1025, thence to ground at the middle left front contact of relay 920. The sequence switch thereupon starts to rotate and under the control of cam 1058 rotates through two complete revolutions. As the sequence switch passes through positions $1\frac{3}{4}$ to $5\frac{1}{4}$ during its first revolution, pulses of the station's code series are transmitted and since the station's letter was assumed to be W and a single register relay 1120 is therefore energized, a code comprising a heavy and a weak negative impulse is transmitted. As sequence switch 1020 passes through positions $1\frac{3}{4}$ to $2\frac{1}{4}$, both sides of the fundamental circuit are grounded since for the letter W, no first positive pulse is transmitted. Ground is applied to the tip side of the fundamental circuit by way of conductors 926, 1027, the left contact of cam 1029, and the outer left back contact of relay 1121, and to the ring conductor 925 over the right front contact of relay 916, the inner left front contact of relay 920, the left front contact of relay 922, conductor 927 to ground at the left contact of cam 1028. When the sequence switch passes through positions $2\frac{3}{4}$ to $3\frac{1}{4}$, negative potential is applied to the ring side of the fundamental circuit as follows: from the call indicator 1429, conductor 1431, the middle front contact of relay 1403, conductors 118 and 129, thence as traced to conductor 925, right front contact of relay 916, inner left front contact of relay 920, left front contact of relay 922, conductor 927, the lower contacts of cams 1030 and 1031, high resistance 1032 to battery. Since the register relay 1120 is energized, a branch of this circuit in parallel with the high resistance 1032, extends over the upper contact of cam 1033, the outer right back contact of relay 1121, the inner right front contact of relay 1120 to battery through the 130

- low resistance 1105. The tip side of the fundamental circuit extends from the call indicator over conductor 1430, the upper front contact of relay 1403, conductors 117 and 128 thence as traced over conductors 913 and 926 to ground at the left contact of cam 1028. As sequence switch 1020 passes through positions $3\frac{3}{4}$ to $4\frac{1}{4}$, the tip side of the fundamental circuit is connected to 9 $\frac{1}{4}$, conductor 913 is connected over conductor 926 to ground at the left contact of cam 1028 and 70 conductor 913 is connected to battery over conductor 927 thence by parallel paths, one extending over the lower contacts of cams 1030 and 1031 through the high resistance 1032 and the other path over the right contact of cam 1035, conductor 1037, the outer right contact of relay 1206, the outer right front contact of relay 1204 75 through the low resistance 1105. The resultant impulse of current is therefore of negative potential and heavy.
- During the movement of sequence switch 1020 from position $9\frac{3}{4}$ through position 80 13 $\frac{1}{4}$, impulses of the hundreds code series are transmitted. It was assumed that the hundreds digit was 6 and therefore, a code comprising a positive, a weak negative and a heavy negative impulse is transmitted. 85 As the sequence switch rotates through positions $9\frac{3}{4}$ to $10\frac{1}{4}$, conductor 925 of the fundamental circuit is extended over conductor 927, to ground at the right contact of cam 1028 and conductor 913 is extended over 90 conductor 926, the left contact of cam 1038, conductor 1039, the outer left front contact of relay 1211, the outer right front contact of relay 1210, to battery through the high resistance 1106, resulting in the transmission 95 of a weak impulse of positive potential. As the sequence switch rotates through positions $10\frac{3}{4}$ to $11\frac{1}{4}$, conductor 913 is extended to ground over conductor 926 and the left contact of cam 1028, and conductor 925 is 100 extended to battery over conductor 927, the lower contacts of cams 1030 and 1031 through high resistance element 1032. Since the branch of this circuit over the left contact of cam 1040 and conductor 1041 is open 105 at contacts of relays 1211 and 1212, a weak negative impulse is transmitted. As the sequence switch rotates through positions $11\frac{3}{4}$ to $12\frac{1}{4}$, conductor 925 is connected to ground over conductor 927 and the right contact of cam 1028 and conductor 913 is 110 also connected to ground over conductor 926, the right contact of cam 1038, conductor 1042 to ground at the outer left front contact of relay 1210. As the sequence 115 switch rotates through positions $12\frac{3}{4}$ to $13\frac{1}{4}$, conductor 913 is connected to ground over conductor 926 and the left contact of cam 1028 and conductor 925 is extended over conductor 927, the lower contacts of cams 120 1030 and 1031, through high resistance 1032 to battery, and in parallel with the high resistance 1032 over the right contact of cam 1040, conductor 1043, the outer right contact of relay 1213, to battery through the low resistance 1105. The resultant impulse 125 is of heavy negative potential.
- During the movement of sequence switch 1020 from position $13\frac{3}{4}$ through position 130 17 $\frac{1}{4}$, impulses of the tens code series are

transmitted. The tens digit, having been assumed to be 4, a code comprising a weak negative, a weak positive and a second weak negative impulse is transmitted. From position 13 $\frac{3}{4}$ through position 14 $\frac{1}{4}$, both conductors 913 and 925 are grounded, the conductor 925 being extended to ground through the right contact of cam 1028 and conductor 913 extended to ground over conductor 926, 5 the left contact of cam 1044, conductor 1045 and the outer left back contact of relay 1100. As sequence switch 1020 rotates from position 14 $\frac{3}{4}$ to position 15 $\frac{1}{4}$, conductor 913 is extended to ground over the left contact of cam 1028 and conductor 925 is extended over conductor 927, the lower contacts of cams 1030 and 1031 through high resistance 1032 to battery. Since the shunt path over the left contact of cam 1046 is open at contacts of relays 1101 and 1102, the resultant impulse is of weak negative potential. When sequence switch 1020 rotates from position 15 $\frac{3}{4}$ to position 16 $\frac{1}{4}$, conductor 925 is extended to ground over the right contact of cam 1028 and conductor 913 is extended over conductor 926, the right contact of cam 1044, conductor 1047, the left front contact of relay 1102, the inner left contact of relay 1101, the outer right back contact of relay 1100 to battery through the high resistance element 1106 thereby transmitting a weak positive impulse. In passing through positions 16 $\frac{3}{4}$ to 17 $\frac{1}{4}$, conductor 913 is connected to ground at the left contact of cam 1028 and conductor 913 is extended over conductor 927, the lower contacts of cams 1030 and 1031 through high resistance 1032 to battery. Since the branch of this circuit extending over the right contact of cam 1046 is open at the left contact of register relay 1103, no low resistance shunt is established around resistance 1032 and the impulse transmitted is therefore of weak negative potential. As sequence switch 1020 leaves position 16, the holding circuit of relays 921 and 922 previously traced is opened at the upper left contact of cam 1022 and these relays thereupon release. Following the release of relay 922, conductors 913 and 925 40 of the fundamental circuit are extended over contacts of cams 1053 and 1054 to the impulse cams of sequence switch 1020. When the sequence switch 1020 rotates from position 17 $\frac{3}{4}$ to position 1 $\frac{1}{4}$, impulses of the units code series are transmitted. The units digit having been assumed to be 7, a code comprising two heavy negative impulses is transmitted. From position 17 $\frac{3}{4}$ through position 18 $\frac{1}{4}$, both conductors 913 and 925 are grounded, conductor 925 over conductor 930, the lower left contact of cam 1053, and the right contact of cam 1028 and the conductor 913 over conductor 931, the right contact of cam 1054, conductor 1027,

the left contact of cam 1048, conductor 1049, 65 the outer left back contact of relay 1111 to ground. As the sequence switch rotates through positions 18 $\frac{3}{4}$ to 19 $\frac{1}{4}$, conductor 913 is connected to ground over the left contact of cam 1028, and conductor 925 is 70 extended over conductor 927, the lower contacts of cams 1030 and 1031, through high resistance 1032 to battery. A branch of this circuit also extends over the lower contact of cam 1030, the left contact of cam 1050, 75 conductor 1051, the outer right back contact of relay 1111, the inner right front contact of relay 1110, to battery through the low resistance 1105. The resultant impulse is of heavy negative potential. As the sequence switch rotates from positions 19 $\frac{3}{4}$ to 20 $\frac{1}{4}$, both conductors 913 and 925 are again 80 grounded, the conductor 925 over the right contact of cam 1028 and the conductor 913 over conductor 1027, the right contact of cam 1048, conductor 1053, through the left back contact of relay 1112. As the sequence switch rotates from position 20 $\frac{3}{4}$ through 85 normal to position 1 $\frac{1}{4}$, conductor 913 is connected to ground over the left contact of cam 1028 and conductor 925 is extended over 90 the left contact of cam 1053, conductor 927, next to the outer right back contact of relay 921, conductor 932, contacts of cam 1031, resistance 1032 to battery and by a branch of 95 this circuit over the right contact of cam 1050, conductor 1055, the left front contact of relay 1113 through low resistance 1105 to battery. The resultant impulse is negative and heavy. 100

The complete designation has now been transmitted to the call indicator in the manual office 1450 and the sequence switch 1020 continuing to complete its second revolution, again grounds conductors 913 and 925 as it 105 passes from position 1 $\frac{1}{2}$ to position 1 $\frac{3}{4}$, the conductor 913 being connected to ground as traced through the right back contact of relay 922, thence over the middle right back contact of relay 928 to ground at the lower contact of cam 1056, and conductor 925 being connected to ground as traced over conductor 930, lower left contact of cam 1053 and the right contact of cam 1028. As 110 soon as the sequence switch leaves position 1 $\frac{3}{4}$, both conductors 913 and 925 are opened. When sequence switch 1020 leaves position 3 $\frac{1}{2}$, the locking circuit of relay 920 is opened at the lower contact of cam 1057, and since the initial circuit of relay 920 115 was opened upon the deenergization of relay 921, relay 920 now deenergizes disconnecting conductors 913 and 925 and removing the shunt from around relay 430. Relay 920 also opens the driving circuit of sequence switch 1020 extending over the upper left contact of cam 1026, but the switch 120 125 1020 is driven through position 6 by a cir-

cuit over the lower left contact of cam 1058 to ground at the left contact of relay 901 and into its normal position over the lower right contact of cam 1058. In position 1, 5 the circuit over the upper left contact of cam 1026 being now open at relay 920, the sequence switch is arrested in its normal position.

Relay 430 upon operating, removes battery potential, from conductor 208, and connects ground through its left front contact to this conductor, whereupon a circuit is completed from ground at the left front contact of relay 430 over the right contact 10 of relay 427, conductor 208, brush 202, conductor 131, middle left contact of relay 112, to battery through the upper winding of relay 119. Relay 119 energizes cutting through the tip and ring conductors 117 15 and 118 of the trunk circuit to the tip and ring strands of the operator's cord circuit, and locks itself over its lower winding and lowermost front contact to ground at the outer left front contact of relay 112. Relay 112 being locked over a circuit extending 20 from battery through its right front contact to ground at its inner left front contact and relay 119 being locked as described, these relays remain locked until relay 112 is shunted through the operation of relay 123 25 as will hereinafter appear. Relay 430 upon energizing, also opens the locking circuit of relay 409 permitting its release. As soon as relay 409 deenergizes, it removes the shunt from around relay 525 permitting it 30 to energize in a locking circuit of relay 526. Relay 525 at its two left inner front contacts establishes circuits through the windings of relay 533 and the windings of 35 relays 904 and 905 for initiating the release of the switching unit. The circuit through the left winding of relay 533 may be traced from ground through the left winding of this relay, the middle left contact of relay 45 525, the inner right contact of relay 425, brush 406, winding of relay 905, brush 1002, conductor 1209 to battery at the inner right contact of relay 900. The circuit through the right winding of relay 533 may be traced 40 through the inner left contact of relay 525, the outer right contact of relay 425, brush 404, winding of relay 904, and thence as traced to battery at the inner right contact of relay 900. Relays 533, 904 and 905 energize, 45 relays 904 and 905 cooperating to close a circuit from ground over the left contacts of these relays through the right winding of relay 906 to battery. Relay 906 energizes and locks over its left winding and inner 50 left front contact, conductor 909, to ground through the brush 1007. Relay 906 also extends the circuit previously traced through relays 904 and 905 through its next to outer left contact, directly to battery at the inner 55 right contact of relay 900 independent of the brush 1002, and closes a circuit for the stepping magnet 1001 of the control switch 1000 extending from battery through the magnet and its contact, next to inner contact of relay 906 to ground through the brush 1007. The magnet 1001 intermittently 60 opens and closes its own circuit and advances the switch brushes to the next normal position when ground is disconnected from brush 1007. Locking ground is now 65 removed from relays 906 and 901 and these relays deenergize. Relay 901 upon deenergizing, removes busy ground potential from the test terminals in the banks of sender 70 selectors such as 400 and opens the locking circuits of relays 900 and 902. Relay 900 upon deenergizing, removes battery potential from conductors 1104 and 1209 releasing all register relays of Figs. 11 and 12 which 75 are in an operated condition. Since relay 916 deenergized as soon as switch 1000 advances to position 5, all apparatus of the sender is now in normal condition.

When relay 533 energizes, it closes a circuit extending from ground at its front contact through the winding of relay 416, to battery at the outer right contact of relay 417. Relay 416 energizes closing a circuit from ground through its contact and the winding of relay 415, the winding of relay 80 416, and to battery as traced. Relay 415 being shunted at the contact of relay 533, does not energize until relay 533 deenergizes following the restoration of the sender. When relay 415 energizes, it removes ground 85 at its right back contact permitting the release of relays 425 and 432, and in turn the release of relays 429 and 430, 408, 417, 413 and 310. The release of relay 417 opens the circuit of relays 415 and 416, whereupon 90 they also deenergize. Relay 413 upon deenergizing, opens the circuit of relay 414. All apparatus of the switching unit is now 95 in normal condition since the sender selector 400 and the trunk selector 200 do not restore to normal but remain in the position 100 in which they are last used.

At the terminating operator's position, following the complete transmission of impulses for setting the call indicator, relay 115 1403 becomes deenergized in the well known manner disconnecting the call indicator from conductors 117 and 118 of the trunk circuit and connecting such conductors to the left windings of repeating coil 1402. 120 Since at this time relay 1401 is energized and battery and ground connections are disconnected from the conductors of trunk 117 and 118, the deenergization of relay 1403 is not effective at this time to cause an erroneous 125 operation of supervisory relay 120 of the cord circuit 150.

The terminating operator noting the number displayed on her call indicator tests the jack of the indicated line with the tip of 130

- plug 1414 to determine if the line is idle or busy. Assuming that the line tests idle she then inserts the plug 1414 in the jack 1415 whereupon a circuit is extended from ground through the winding of cut-off relay 1426, sleeve contacts of jack 1415 and plug 1414, winding of relay 1416 to battery through the winding of relay 1417. Relay 1416 upon energizing, closes an obvious circuit for relay 1409 which at the back contact of its inner right armature opens the circuit of lamp 1405 thereby extinguishing it. At the front contact of this armature, a circuit is prepared for the disconnect lamp 1418. At its outer right back contact, relay 1409 opens the locking circuit of relay 1407 which thereupon deenergizes. At its left back contact, relay 1409 opens the circuit previously traced through the right winding of relay 1401, relay 1401 thereupon deenergizing, connecting the windings of relay 1400 to the conductors 117 and 118 of the trunk circuit, causing the energization of supervisory relay 120 of the toll operator's cord circuit and the illumination of lamp 121 as a ringing signal to the toll operator.
- In response to the ringing signal, the toll operator depresses ringing key 122 applying ringing current to the tip and ring strands of her cord circuit, whereupon ringing relay 1412 operates over a circuit extending from the source of ringing current 126, the lower contact of ringing key 122, ring contact of plug 106 and jack 107, upper front contact of relay 119, conductor 117, upper back contact of relay 1403, upper left winding of repeating coil 1402, winding of ringing relay 1412, condenser 1413, lower left winding of repeating coil 1402, intermediate back contact of relay 1403, conductor 118, innermost lower front contact of relay 119, outer left back contact of relay 110, tip contacts of jack 107 and plug 106 to ground at the upper contact of ringing key 122. At this time, the tip and ring contacts of jack 107 are bridged through the intermediate lower contact of relay 119, high impedance coil 124 and the right front contact of relay 108 for the purpose of preventing the release of relay 1400 and the consequent operation of disconnect lamp 1418 and the release of the terminating operator's circuit due to the opening of the toll operator's cord circuit at the time she depressed ringing key 122. Upon the energization of relay 1412, an obvious circuit is established through the left winding of relay 1401, which establishes a local holding circuit for relay 1400 for preventing the release of relay 1400 and the prevention of a false disconnect signal. In parallel with the circuit through the left winding of relay 1401, a circuit is established through the upper winding of ringing relay 1420. Relay 1420

upon energizing, locks through its lower winding, its innermost lower armature, the outer right back contact of relay 1419, the outer right contact of relay 1411 to ground at the left front contact of relay 1409. As soon as key 122 is released, relay 1412 de-energizes and releases relay 1401 which reconnects battery and ground through relay 1400 to the trunk circuit. Relay 120 again operates to illuminate lamp 121.

It being assumed that the plug 1414 has been inserted in the jack corresponding to station W of the indicated line, which is to receive ringing current in accordance with a two-ring code and relay 1417 being therefore deenergized, as soon as ringing relay 1420 energizes, a circuit is established from ground through its innermost upper front contact, the outer left armature and contact of relay 1419, winding of relay 1428, the normal right contact thereof, the right back contact of relay 1417, through the pickup interrupter 1422. Relay 1421 upon energizing, closes a locking circuit for itself through its right contact independent of interrupter 1422. A circuit is now established for applying ringing current from the source 1423 to the called line through the interrupter 1424 over the left front contact of relay 1428, the left back contact of relay 1417, through the ringing cut-off relay 1421, the inner left back contact of relay 1419, the lowermost front contact of relay 1420, ring contacts of plug 1414 and jack 1415 through the call bell of the wanted substation to ground. This current is applied to the called line in accordance with a two-ring code until the called party responds when relay 1421 energizes, opening the shunt around the winding of relay 1419. Relay 1419 thereupon energizes over a circuit from battery through its winding to ground at the left front contact of relay 1409 and opens the circuit over which ringing current was applied, at the back contact of its inner left armature. Relay 1419 also opens the locking circuits of relays 1420 and 1428 whereupon these relays de-energize. As soon as relay 1420 deenergizes, the ringing current leads are disconnected from the strands of the cord circuit and the tip and ring contacts of plug 1414 are connected through to the right windings of repeating coil 1402.

A circuit is now established for supervisory relay 1427 extending from battery through the winding of this relay, lower right winding of repeating coil 1402, lowermost back contact of relay 1420, ring contacts of plug 1414 and jack 1415 thence over the called subscriber's line loop and returning through the tip contacts of jack 1415 and plug 1414, the upper contact of relay 1416, the upper back contact of relay 1420,

to ground through the upper right winding of repeating coil 1402. Relay 1427 upon energizing establishes a circuit through the right winding of relay 1401, to ground 5 through the intermediate right front contact of relay 1411 causing the energization of relay 1401, which thereupon disconnects the windings of relay 1400 from the conductors of the trunk circuit for 10 the purpose of releasing relay 120 and extinguishing the lamp 121 at the toll operator's position indicating that the called party has responded.

On completion of the conversation, the 15 toll operator receives a disconnect signal from the calling subscriber and removes the plugs 104 and 106 from the jacks 103 and 107 respectively. As soon as plug 106 is removed from jack 107, relay 108 deenergizes closing a circuit for bridging relay 123 across conductors 117 and 118 of the trunk circuit. If at this time, the called subscriber has restored his receiver to the switchhook and relays 1427 and 1401 are 20 deenergized, the circuit of relay 123 is completed from battery through the left winding of relay 1400, the left back contact of relay 1401, the upper left winding of repeating coil 1402, the upper left back contact of relay 1403, conductor 117, the upper 25 front contact of relay 119, the intermediate lower front contact of relay 119, winding of relay 123, right back contact of relay 108, the outer left back contact of relay 110, the 30 innermost lower front contact of relay 119, conductor 118, the intermediate armature and back contact of relay 1403, the lower left winding of repeating coil 1402, the right back contact of relay 1401, to ground 35 40 through the right winding of relay 1400. Relay 123 upon operating, connects ground through both terminals of relay 112 shunting this relay and causing its deenergization. Relay 112 upon deenergizing, opens 45 the locking circuit of relay 119 which in turn releases. With relays 108 and 112 both deenergized the ground potential is removed from the multiples of terminal 111 and from conductor 130 whereupon the trunk 50 circuit is made available for other toll connections. As soon as relay 119 deenergizes, the circuit previously traced through relays 123 and 1400 is opened and these relays release, relay 1400 in turn opening the locking circuit of relay 1411. When relay 1411 deenergizes, a circuit is completed for the 55 disconnect lamp 1418 extending from ground through the intermediate right back contact of relay 1411, lamp 1418 to battery through the inner right front contact of relay 1409. The operator noting the 60 illumination of the disconnect lamp 1418, removes the plug 1414 from the jack 1415, whereupon relays 1426, 1416, 1409 and 1419 release, and lamp 1418 becomes extin-

guished. All of the apparatus employed in the establishment of the connection is now restored to normal condition.

Allotment of an idle switching unit.

Consideration will next be given to the manner in which the switching units are allotted for use. Following the unbalancing of coil 812 it will be recalled the relay 809 was operated and a circuit closed for relay 508 to start the operator's position selector 500 in motion. Relay 508, on energizing, closes a circuit from battery through the right back contact of relay 525, left back contact of relay 526, conductor 532, outer 80 left contact of relay 508, conductor 819 to a point between the upper winding of the balancing coil and the polarized relay 814. Current flowing over this circuit is in such a direction as to cause the polarized relay 814 to restore its armature, opening the circuit of relay 809. Current is removed from the balancing coil by the energization of relay 612 and the energization of relay 526, which occur in the manner hereinbefore described.

At the time relay 520 is operated the following circuit is closed: ground, through the left front contact of relay 520, conductor 816, brush 802 of the allotter switch 800, thence in parallel to the winding of relay 808 and the contact and winding of relay 801 to battery. Relay 808 attracts its armature and removes ground from conductor 824 so that the energization of any 100 relay, such as relays 809, 810, etc., will be without effect to cause the energization of one of the relays 508, 518, etc., until a new switching unit has been allotted. Stepping magnet 801 interrupts its own circuit and 105 advances the allotter switch 800 from position to position until the test brush 802 encounters a terminal identifying an idle switching unit. When an idle unit is found the allotter switch ceases to rotate and relay 110 110 808 becomes deenergized.

Extension of connections to lines numbered above 10,000.

If a number is registered on the registers of the sender for a line numbered above 10,000, the first digit registered will be 1, and relays 1200, 1201 and 1204 will operate as described in connection with the preceding call. The second digit will be zero and 115 no relays of the group 1205, 1210, 1211, 1212 and 1213 will be operated. When thereafter the control switch 1000 reaches position 5 following the registration of the fifth digit of the wanted number, relays 902 and 916 120 will function as before and, in addition, a circuit is established for operating relays 928 and 1206. This latter circuit extends in parallel from battery, through the winding 125 of relays 928 and 1206, through the left con- 130

tact of relay 1204, the outer right back contacts of relays 1202 and 1203, the outer left back contacts of relays 1213, 1212 and 1205, conductor 1217, brush 1005 of switch 1020, 5 inner left back contact of relay 906, conductor 909 to ground through brush 1006. With relay 1206 energized, a circuit is established over its next to inner right front contact, conductor 1218, right contact of 10 cam 1026 to battery, through the winding of sequence switch magnet 1020. The sequence switch advances out of its normal position and, under the control of the right contact of cam 1058, advances into position 15 5. In position 5, the previously traced circuit, through the contact of relay 1206 is opened, and the sequence switch stops in position 5. When the toll operator plugs into the selected trunk jack 107, relay 918 20 operates as before, causing the operation of relays 919, 920 and 921. When the distant operator responds by depressing the display key of the selected trunk, relays 918 and 919 deenergize, thereby closing the previously traced circuit for relay 920. Relay 920 thereupon energizes and locks as before, and at its middle left front contact closes a circuit extending over the upper left contact of cam 1026 for advancing sequence switch 25 39 1020 out of position 5. Switch 1020 is thereupon advanced under the control of cam 1058 into its normal position where the circuits over the upper left contact of cam 1026 is again effective to drive the sequence switch through a second revolution into its 35 normal position.

It will be recalled from the preceding description that, as sequence switch 1020 rotated from position $5\frac{3}{4}$ through position 40 $9\frac{1}{4}$, impulses were transmitted in accordance with the energized and deenergized condition of register relays 1200, 1201, 1202, 1203, 1204, 1207 and 1208. Therefore, since by the operation of relay 1206, the sequence 45 switch was preliminarily advanced to position 5 and started from that position at the time the distant manual operator signaled that her position apparatus was in position to receive impulses, the first digit registered 50 on the relays 1200, etc., is transmitted as the ten-thousands digit. Ordinarily, the codes of impulses transmitted for the several digits of the thousands series differ from the codes of impulses transmitted for the other 55 digit series. Since, therefore, the relays previously employed for registering the thousands digit are now being used to control the transmission of impulses for the ten-thousands digit, it is necessary to modify the 60 circuits controlled by this group of register relays. This modification is, of course, necessary only for the digit 1, this being the only ten-thousands digit employed, and is accomplished through the operation of relay 1206.

It will be recalled that for the thousands digit 1 a code comprising a weak negative followed by a heavy negative impulse was transmitted. For the ten-thousands digit 1, it is now necessary to transmit a code comprising a positive impulse followed by two weak negative impulses. As the sequence switch passes through positions $5\frac{3}{4}$ to $6\frac{1}{4}$, conductor 925 is extended to ground over the right contact of cam 1028 and conductor 70 913 is extended over conductor 1027, the left contact of cam 1060, conductor 1034, the outer left contact of relay 1200, the outer left front contact of relay 1201, the inner right front contact of relay 1206 to battery 75 through the high resistance 1106. As the sequence switch passes through positions $6\frac{3}{4}$ to $7\frac{1}{4}$, conductor 913 is extended to ground over the left contact of cam 1028 and conductor 925 is extended over conductor 927, 80 the lower contacts of cams 1030 and 1031, high resistance 1032 to battery. As no shunt exists around the high resistance 1032 over the left contact of cam 1035 and contacts of the register relays, the impulse is 85 weak and of negative polarity. As the sequence switch passes through positions $7\frac{3}{4}$ to $8\frac{1}{4}$, both the conductors 913 and 925 are grounded, conductor 925 being extended to ground over the right contact of cam 1028 90 and conductor 913 over conductor 1027, the right contact of cam 1060, conductor 1036 and the outer right back contact of relay 1208. As the sequence switch passes through positions $8\frac{3}{4}$ to $9\frac{1}{4}$, conductor 913 95 is extended to ground over the left contact of cam 1028 and conductor 925 is extended over conductor 927, the lower contacts of cams 1030 and 1031, resistance 1032 to battery. No shunt of the high resistance 105 1032 is established at this time over the right contact of cam 1035 and conductor 1037 since relay 1206 has opened its outer right back contact. The resultant impulse is 110 therefore weak and of negative polarity. As the sequence switch continues to rotate from position $9\frac{3}{4}$, through normal to position $1\frac{1}{4}$ of its second revolution, impulses of the thousands, hundreds and tens series are transmitted as determined by the 115 operated and non-operated condition of the register relays of the groups 1210, 1211, etc., 1100, 1101, etc., and 1110, 1111, etc. When sequence switch 1020 passes through positions $1\frac{3}{4}$ to $5\frac{1}{4}$ of its second revolution, the 120 relay 928 being now energized and relays 921 and 922 having deenergized following the passage of the sequence switch through position 16 of its first revolution, conductor 913 of the fundamental circuit is extended 125 over the left contact of relay 916, the outer left front contact of relay 920, conductor 931, the right back contact of relay 922, the middle right front contact of relay 928, conductor 933, left contact of cam 1054, 130

thence directly to ground over the left contact of cam 1028, as the sequence switch passes through positions $2\frac{3}{4}$ to $3\frac{1}{4}$ and again through positions $4\frac{3}{4}$ to $5\frac{1}{4}$ or through contacts of cam 1029 in positions $1\frac{3}{4}$ to $2\frac{1}{4}$ and $3\frac{3}{4}$ to $4\frac{1}{4}$ either to ground at contacts of the register relays of the group 1120, 1121, etc., or to battery through the high resistance 1106 in accordance with the digit code to be transmitted. Conductor 925 is at this time extended over the right contact of relay 916, inner left front contact of relay 920, left back contact of relay 922, outer right front contact of relay 928, conductor 934, the right contact of cam 1053 to ground directly through the right contact of cam 1028 as the sequence switch passes through positions $1\frac{3}{4}$ to $2\frac{1}{4}$ and again through positions $3\frac{3}{4}$ to $4\frac{1}{4}$, or to battery over the lower contact of cam 1030 in positions $2\frac{3}{4}$ to $3\frac{1}{4}$ and the lower contact of cam 1031 or to battery over the right contact of cam 1053, conductor 927, the outer back contact of relay 921, conductor 929, the upper contact of cam 1030 closed in positions $4\frac{3}{4}$ to $5\frac{1}{4}$ and the lower contact of cam 1031. These latter battery connections may be modified by shunt circuits through the low resistance 1105, over the contacts of cam 1033, depending upon the operated or non-operated condition of relays of the group 1120, 1121.

When sequence switch 1020 reaches position $5\frac{3}{4}$ following the transmission of the last or units series of impulses, both conductors 913 and 925 are extended to ground. Conductor 913 extends to ground over the left contact of relay 916, the outer left front contact of relay 920, conductor 931 and the lower contact of cam 1059, and conductor 925 extends to ground as traced over the outer right front contact of relay 928, conductor 934, the right contact of cam 1053 and the right contact of cam 1028. As soon as the sequence switch passes through position $5\frac{3}{4}$, both conductors 913 and 925 are opened. From this point, the sender functions as previously described and the connection is established and released in the same manner as described in connection with the preceding call.

Common time alarm.

For the purpose of bringing up an alarm after a predetermined time interval following the seizure of a switching unit for use, if the call does not progress satisfactorily, a timing circuit, shown in Fig. 13, is provided common to a plurality of link circuits and to a common alarm device. For this purpose there are provided two groups of timing leads extending from the switching units and from the common alarm device, shown enclosed within the broken lines in the upper left corner of Fig. 13. One of

these groups 1313 comprises the so-called "A" timing leads which initiate the beginning of the time interval, and the other group 1314 comprises the so-called "B" timing leads which measure the termination of the time interval. Each of the timing leads are multiplied, as the case may be, to relays of either a group of switching units or to relays of an alarm device. Thus, for example, with thirty-five switching units multiplied to each of a pair of "A" and "B" leads, the timing circuit as disclosed is capable of serving an alarm device and two hundred and nine switching units. If a larger number of switching units is to be served additional timing leads will be added and additional relays corresponding to the relays 1309 and 1312, inclusive. The transfer switch 1315 is provided, for the purpose of transferring the timing leads and other associated testing conductors, to an emergency timing circuit in case of failure of the regular timing circuit.

It will be recalled that immediately following the depression of the office key 601 by the toll operator, the allotted switching unit, disclosed in Figs. 2, 3, 4 and 5, was taken for the use of the operator, and relay 408 became energized, in turn operating the start relay 417. With relay 417 energized a circuit was established over conductor 433, extending to the common timing circuit. This circuit may be traced from ground, at the inner left contact of relay 417, conductor 433, a contact of switch 1315, to battery through the winding of relay 1300. Relay 1300 energizes connecting ground to the common ground lead 1316 and establishes a circuit for relay 1301 extending through the ringing machine 1317. Through the operation of the ringing machine, relay 1301 intermittently energizes and de-energizes. Upon the first energization of relay 1301, a circuit is closed from ground at its contact, through the left back contact of relay 1303, the left windings of relays 1302 and 1303, to battery. Relay 1302 energizes but relay 1303 does not receive sufficient current. Upon the energization of relay 1302 a circuit is established from battery, through the left winding of relays 1303 and 1302, thence in parallel through the right windings of these relays, the right front contact of relay 1302, to ground on conductor 1316. Relay 1302 is maintained energized over this circuit, but since the right winding of relay 1303 is shunted by direct ground at the contact of relay 1301, relay 1303 remains unoperated. Upon the first opening of the circuit of relay 1301, the shunt is removed and relay 1303 energizes, both relays 1303 and 1302 being now locked over the right contact of relay 1302. Upon the second energization of relay 1301 with relay 1303 energized, relay 1302 is

shunted and becomes deenergized. A circuit is now established for relay 1304 extending from battery, through the left windings of relays 1305 and 1304, the left back 5 contact of relay 1305, outer right contact of relay 1303, right back contact of relay 1302, to ground on conductor 1316. Relay 1304 energizes, locking itself to ground on conductor 1316 and closing a shunt around the 10 right winding of relay 1305. Upon the second deenergization of relay 1301, relay 1303 deenergizes opening the shunt around relay 1305 which thereupon energizes in the locking circuit of relay 1304. When relay 1301 energizes for the third time relay 1302 operates as before, shunting the right winding of relay 1303. Upon the third deenergization of relay 1301, relay 1303 again energizes shunting relay 1302 and 15 locking itself over its left winding to ground at the contact of relay 1301. With relays 1303 and 1305, both energized and relay 1302 deenergized, a shunt is established around relay 1304 extending from the left front 20 contact of relay 1305, outer right front contact of relay 1303, right back contact of relay 1302, to ground on conductor 1316 causing the release of relay 1304. Thus, in response to three energizations of 25 relay 1301 a circuit is established for relay 1307 extending from battery, through the winding of relay 1307, the left back contact of relay 1306, right contact of relay 1305, right back contact of relay 1304, to ground on conductor 1316. Relay 1307 energizes and locks over its 30 left contact through the winding of relay 1306 to ground on conductor 1316. Relay 1306 being shunted does not operate until 35 the next or third deenergization of relay 1301, when relay 1303 releases opening the locking circuit of relay 1305 and in turn opening the ground connection over the left back contact of relay 1306.

40 In response to succeeding fourth etc. energizations and deenergizations of relay 1301, relays 1302 to 1304, inclusive, again operate in the cycle above described, provided relay 1300 is still maintained energized. At the end of the second cycle of 45 operation of the relays of the timing device 1330, but before the sixth energization of relay 1301, with relays 1305 and 1306 energized, a circuit is established for relay 1308 extending from battery, through the winding of relay 1308, the left front contact of relay 1306, right front contact of relay 1305, the right back contact of relay 1304, to ground on conductor 1316. Relay 1308 50 thereupon closes a shunt over its left contact and the left contact of relay 1307, around the winding of relay 1307, causing its deenergization. Relay 1306 is, however, maintained energized, following the deenergization 55 of relay 1307 from battery, over the

left contact of relay 1308. Upon the subsequent release of relay 1305, in response to the sixth deenergization of relay 1301, relay 1308 becomes deenergized in turn opening the circuit of relay 1306.

At the time relay 1307 operated and prior to the operation of relay 1306, a circuit was established from battery in parallel through the windings of relays 1310 and 1311. Relay 1310 upon energizing connects ground 70 from its contacts over contacts of switch 1315 to all of the timing leads of the "A" group 1313, for operating timing relays corresponding to relay 411 of all switching units of the office that are at the time taken for use. The circuit of relay 411 may be traced from battery, middle right front contact of relay 417, right winding of relay 411, conductor 434, contact of switch 1315 to ground through the outer left contact of relay 1310. A circuit is also closed in parallel through the right winding of relay 1321 for lighting the lamp 1322. Through the intermittent operation of relay 1321 under the control of the timing device 1330 75 the lamp 1322 flashes, thereby indicating that the timing device is functioning. Relay 411 upon operating locks over its left contact and left winding to ground at the outer left contact of relay 417.

80 Relay 1311 which energizes in parallel with relay 1310 connects the "B" timing leads of group 1314 through windings of testing relays 1323, 1324 and 1325. Should there be a false or unstandard ground 85 on any of the leads at this time, which would operate to cause a false timing impulse to be transmitted to the switching units connected thereto, the particular testing relay, one of whose windings is connected to such grounded leads, will operate. It will be assumed that such a false ground exists on lead 1326, and that a circuit is 90 therefore effective over this lead, a contact of switch 1315, the inner right contact of relay 1311, a second contact of switch 1315, the right winding of relay 1324 to battery. Relay 1324 operates and locks over its left winding and left contact to ground at the 95 normal contacts of key 1327. Relay 1324 100 also establishes a circuit over its right contact, through the alarm bell 1328 and the ringing machine 1329, whereby an alarm is given that an unstandard condition exists 105 on one of the timing leads. By noting the particular test relay which is operated, the maintenance man is able to locate the point where the trouble exists. When the trouble 110 is corrected and the key 1327 is depressed relay 1324 is unlocked and cuts off the alarm. 115

120 As soon as relay 1306 energizes as hereinbefore described the circuit of relays 1310 and 1311 is opened whereupon relay 1321 deenergizes extinguishing the lamp 1322. Relay 411, however, remains energized fol- 125

lowing the opening of its operating circuit at relay 1310 by reason of its locking circuit. At the end of the second cycle of operation of the timing device 1330, when 5 relay 1308 energizes as above described, an obvious circuit is established in parallel through the windings of relays 1309 and 1312, relay 1312 establishing an obvious circuit through the left winding of relay 10 1321 for lighting the lamp 1322, and connecting ground to all of the "B" timing leads of the group 1314. With the "B" leads grounded all of the "B" timing relays corresponding to relay 418 of all switching units 15 at the time taken for use are operated. The circuit of relay 418 may be traced from grounded battery, over the inner right contact of relay 417, right winding of relay 418, conductor 435, a contact of switch 1315 20 to ground at the outer left contact of relay 1312. Relay 418 upon operating locks over its left contact and winding to ground at the outer left contact of relay 417. Relay 1309 which energized in parallel with relay 25 1312 connects all of the "A" timing leads to the windings of testing relays 1323, 1324 and 1325, in the manner previously described with respect to the connection of the "B" timing leads, for detecting unstandard 30 ground on the "A" leads.

With relays 411 and 418 of the switching unit both energized a circuit is established from ground, through the right contacts of these relays, the left back contact 35 of relay 429, if pulsing has not begun, or over the outer right back contact of relay 430 if pulsing has started to battery through the winding of relay 410. Relay 410 upon operating removes the shunt from the winding of wipe-out relay 425 whereupon the release of the switching unit is immediately caused. At its left front contact, relay 410 also establishes a circuit from ground over conductor 438, to battery through relay 40 418. With relay 1318 energized a circuit is established from battery, through its left contact and the right winding of relay 1319 to the "B" timing lead 1332, and a circuit from battery through the outer right contact of relay 1318, the right winding of relay 1320, to the "A" timing lead 1333. In the manner above described in connection 45 with the operation of relays 411 and 418 the "A" and "B" leads 1332 and 1333 are grounded in succession through the operation of the timing device 1330 whereupon relays 1319 and 1320 both become operated and if relay 410 still remains energized due to the non-release of the switching unit. Relays 1319 and 1320 upon energizing both lock over their left contacts and left windings to battery at the inner right contact of relay 1318, and at their right contacts establish an obvious circuit 50 for relay 1334. Relay 1334 upon operating

closes a circuit through the alarm bell 1335 and the ringing machine 1336 for attracting the attention of the maintenance man to the fact that a switching unit has not 70 released.

In addition relay 1334 establishes a circuit from ground at its left contact over conductor 437, lamp 436, and individual to the switching unit of Figs. 2, 3, 4 and 5, to battery at the inner contact of relay 75 410. The lamp 436 remains lighted until the trouble on the particular switching unit is found, and the switching unit is released.

As soon as the switching unit is released 80 relay 417 unlocks relays 411 and 418 which in turn cause the deenergization of relays 410, 1318, 1319, 1320 and 1334. The deenergization of relay 417 also opens the branch of the starting circuit 433 extending to the switching unit disclosed. If there 85 are no other switching units at the time in use, relay 1300 deenergizes arresting the operation of the timing device 1330.

From the foregoing description of the 90 timing circuit shown in Fig. 13, it is apparent that by the simple addition of relays 1309 and 1311 and the addition of relays 1323, 1324 and 1325, it is possible to 95 test one group of timing leads for unstandard grounds while the timing device is utilizing the timing leads of the other group for timing purposes.

What is claimed is:

1. In a telephone exchange system, a plurality of operators' positions, a sender controlling equipment at each of said positions, a plurality of outgoing trunks, each trunk terminating at its distant end in a manual connection terminal, mechanism associative with the distant ends of said trunks for indicating the numbers of wanted lines, a plurality of senders, a plurality of sender controlling equipments, a plurality of switching units common to said operators' positions, means to operate a switching unit to establish an interconnection between a sender controlling equipment, a sender and an idle trunk, and means to operate said mechanism over said trunk under the control of a sender in accordance with the operation of said sender controlling equipment. 100 105 110 115

2. In a telephone exchange system, a plurality of operators' positions, a sender controlling equipment at each of said positions, a plurality of outgoing trunks, each trunk terminating at its distant end in a manual connection terminal, mechanism associative with the distant ends of said trunks for indicating the numbers of wanted lines, a plurality of senders, a plurality of sender controlling equipments, a plurality of switching units common to said operators' positions, means to operate a switching unit 120 125 130 to establish an interconnection between a

- sender controlling equipment, a sender and an idle trunk, means to indicate to an operator the number of the idle trunk selected, and means to operate said mechanism over said trunk under the control of a sender in accordance with the operation of said sender controlling equipment.
3. In a telephone exchange system, in combination, incoming lines, outgoing trunks, each trunk terminating at its distant end in a manually operable connection terminal, an operator's position, a cord circuit terminating at each end in a manually operable device for interconnecting an incoming line and an outgoing trunk, mechanism associative with the distant ends of said trunks for indicating the numbers of wanted lines, a plurality of variably operable senders for controlling said mechanism over said trunks independent of said cord circuit, and means at said operator's position to control the automatic selection of a trunk and to variably control the setting of said senders for controlling said mechanism.
4. In a telephone exchange system, in combination, incoming lines, outgoing trunks, each trunk terminating at its distant end in a manually operable connection terminal, an operator's position, a cord circuit terminating at each end in a manually operable device for interconnecting an incoming line and an outgoing trunk under the control of said operator's position, mechanism associative with the distant ends of said trunks for indicating the numbers of wanted lines, a plurality of variably operable senders for transmitting series of impulses of varying characteristics over said trunks for controlling said mechanism, and means at said operator's position to control the automatic selection of a trunk and of a sender and to variably control the setting of said senders for controlling said mechanism.
5. In a telephone exchange system, in combination, incoming lines, outgoing trunks, each trunk terminating at its distant end in a manually operable connection terminal, an operator's position, a cord circuit terminating at each end in a manually operable device for interconnecting an incoming line and an outgoing trunk under the control of said operator's position, means associative with the distant ends of said trunks for indicating the numbers of wanted lines, a plurality of senders for transmitting series of impulses of varying characteristics over said trunks for controlling said mechanism, registers in said sender for recording the digits of wanted line numbers, and means at said operator's position to control the automatic selection of a trunk and of a sender and for variably controlling the setting of said registers for controlling said mechanism.
6. In a telephone exchange system, a plurality of operators' positions, a sender controlling equipment at each of said positions, a plurality of outgoing trunks, each trunk terminating at its distant end in a manually operable connection terminal, mechanism associative with the distant ends of said trunks for indicating the numbers of wanted lines, a plurality of senders, a plurality of sender controlling equipments, a plurality of switching units common to said operators' positions, means to operate a switching unit to establish an interconnection between a sender controlling equipment, a sender and an idle trunk, means to operate said mechanism over said trunk under the control of a sender in accordance with the operation of said sender controlling mechanism, and means operative following the completion of the operation of said sender to release said switching unit.
7. In a telephone exchange system, a plurality of operators' positions, a sender controlling equipment at each of said positions, other operators' positions a plurality of outgoing trunks, said trunks terminating at said latter positions in manually operable connection terminals, mechanism associative with the distant ends of said trunks for indicating the numbers of wanted lines, a plurality of senders, a plurality of sender controlling equipments, a plurality of switching units common to said first operators' positions, means to operate a switching unit to establish an interconnection between a sender controlling equipment, a sender and an idle trunk, means to operate said mechanism over said trunk under the control of a sender in accordance with the operation of said sender, controlling mechanism, and means operative upon the response of a second mentioned operator to start said sender into operation.
8. In a telephone exchange system, a plurality of incoming lines, a plurality of outgoing trunks, each trunk terminating at its distant end in a manually operable connection terminal, means for interconnecting said lines and trunks, mechanism associative with the distant ends of said trunks for indicating the numerical designation of a desired line, a register sender, groups of relay registers for said sender, means for registering the numerical designation of a desired line on said registers, means associated with said sender for transmitting over said trunks a plurality of series of impulses of varying characteristics corresponding to the numerical designations registered upon said registers for controlling said mechanism, and means for changing the order of transmission of said series of impulses.
9. In a telephone exchange system, a plurality of incoming lines, a plurality of outgoing trunks, each trunk terminating at

- its distant end in a manually operable connection terminal, means for interconnecting said lines and trunks, mechanism associable with the distant ends of said trunks for indicating the numerical designation of a desired line, a register sender, groups of relay registers for said sender, means for registering the numerical and stations designations of a desired line on said registers, 5 means associated with said sender for transmitting over said trunks a plurality of series of impulses of varying characteristics corresponding to the designations registered on said registers for controlling said mechanism, and means for changing the order of transmission of said series of impulses in accordance with the operated condition of the relays of certain of said registers. 10. In a telephone exchange system, a calling office, a plurality of distant offices, trunks extending from said calling office to each of said distant offices, responsive mechanism at said distant offices controllable over said trunks, a plurality of controlling means 20 at said calling office, each selectable for connection to the outgoing ends of said trunks, a timing mechanism common to all of said controlling means for measuring a period sufficient for the complete functioning of any of said controlling means, and means operable upon the elapse of the measured period for operating an alarm in the event that a selected controlling means has not completely functioned. 30 11. In a telephone exchange system, a calling office, a plurality of distant offices, trunks extending from said calling office to each of said distant offices, responsive mechanism at said distant offices controllable over said trunks, a plurality of groups of controlling means at said calling office, each controlling means being selectable for connection to the outgoing ends of said trunks, a timing mechanism common to all of said controlling means for measuring a period sufficient for the complete functioning of any of said controlling means, timing leads extending from said timing mechanism to each group of controlling means, and means 40 operable upon the elapse of the measured period for operating an alarm in the event that a selected controlling means has not completely functioned. 50 12. In a telephone exchange system, a calling office, a plurality of distant offices, trunks extending from said calling office to each of said distant offices, responsive mechanism at said distant offices controllable over said trunks, a plurality of controlling means 55 at said calling office, each selectable for connection to the outgoing ends of said trunks, a timing mechanism common to all of said controlling means for measuring a period sufficient for the complete functioning of any of said controlling means, a common start circuit for starting said timing mechanism, means for closing said start circuit upon the selection of any of said controlling means for use, and means operative upon the elapse of the measured period for 60 operating an alarm in the event that a selected controlling means has not completely functioned. 65 13. In a telephone exchange system, a calling office, a plurality of distant offices, trunks extending from said calling office to each of said distant offices, responsive mechanism at said distant offices controllable over said trunks, a plurality of controlling means at said calling office, each selectable for connection to the outgoing ends of said trunks, a timing mechanism common to all of said controlling means for measuring a period sufficient for the complete functioning of any of said controlling means, a common start circuit for starting said timing mechanism upon the selection of any of said controlling means for use, two groups of timing leads extending from said timing mechanism to said controlling means, the leads of one group for marking the commencement of said allotted period in any of said controlling means and the leads of the second group for marking the termination of said allotted period, and means in said timing mechanism for testing the leads of one of said groups for unstandard conditions while the other group is functioning in the transmittal of timing impulses. 80 14. In a timing device for a telephone exchange system, two groups of timing leads extending therefrom, means for transmitting an impulse over each of the leads of one group and at a predetermined interval thereafter an impulse over each of the leads of the second group, and means for testing the leads of each group for unstandard conditions during the transmittal of impulses over the leads of the other group. 90 15. In a timing device for a telephone exchange system, two groups of timing leads extending therefrom, means for transmitting an impulse over each of the leads of one group and at a predetermined interval thereafter an impulse over each of the leads of the second group, means for testing the leads of each group for unstandard conditions during the transmittal of impulses over the leads of the other group, and means for operating an alarm upon the detection of an unstandard condition. 110 16. In a timing device for a telephone exchange system, two groups of timing leads extending therefrom, a relay for connecting ground potential to each of the leads of one group, a second relay for connecting ground potential to each of the leads of the second group, means for operating said relays in 120 125

succession and at predetermined time intervals, testing means; a relay operable with said first relay for connecting the leads of the second group with said testing means, another relay operable with said second relay for connecting the leads of said first group with said testing means, and an alarm device

operable from said testing means if an unstandard ground potential is encountered upon any of said leads.

10

In witness whereof, I hereunto subscribe my name this 27th day of November A. D., 1923.

ALBERT C. POWELL.

DISCLAIMER.

1,577,076.—*Albert C. Powell*, New York, N. Y. TELEPHONE-EXCHANGE SYSTEM. Patent dated March 16, 1926. Disclaimer filed April 4, 1928, by the assignee, *Western Electric Company, Incorporated*.

Hereby enters this disclaimer to that part of the claims in said specification which are in the following words to wit:

“1. In a telephone exchange system, a plurality of operators’ positions, a sender controlling equipment at each of said positions, a plurality of outgoing trunks, each trunk terminating at its distant end in a manual connection terminal, mechanism associable with the distant ends of said trunks for indicating the numbers of wanted lines, a plurality of senders, a plurality of sender controlling equipments, a plurality of switching units common to said operator’s positions, means to operate a switching unit to establish an interconnection between a sender controlling equipment, a sender and an idle trunk, and means to operate said mechanism over said trunk under the control of a sender in accordance with the operation of said sender controlling equipment.

“2. In a telephone exchange system, a plurality of operators’ positions, a sender controlling equipment at each of said positions, a plurality of outgoing trunks, each trunk terminating at its distant end in a manual connection terminal, mechanism associable with the distant ends of said trunks for indicating the numbers of wanted lines, a plurality of senders, a plurality of sender controlling equipments, a plurality of switching units common to said operators’ positions, means to operate a switching unit to establish an interconnection between a sender controlling equipment, a sender and an idle trunk, means to indicate to an operator the number of the idle trunk selected, and means to operate said mechanism over said trunk under the control of a sender in accordance with the operation of said sender controlling equipment.

“3. In a telephone exchange system, in combination, incoming lines, outgoing trunks, each trunk terminating at its distant end in a manually operable connection terminal, an operator’s position, a cord circuit terminating at each end in a manually operable device for interconnecting an incoming line and an outgoing trunk, mechanism associable with the distant ends of said trunks for indicating the numbers of wanted lines, a plurality of variably operable senders for controlling said mechanism over said trunks independent of said cord circuit, and means at said operator’s position to control the automatic selection of a trunk and to variably control the settings of said senders for controlling said mechanism.

“4. In a telephone exchange system, in combination, incoming lines, outgoing trunks, each trunk terminating at its distant end in a manually operable connection terminal, an operator’s position, a cord circuit terminating at each end in a manually operable device for interconnecting an incoming line and an outgoing trunk under the control of said operator’s position, mechanism associable with the distant ends of said trunks for indicating the numbers of wanted lines, a plurality of variably operable senders for transmitting series of impulses of varying characteristics over said trunks for controlling said mechanism, and means at said operator’s position to control the automatic selection of a trunk and of a sender and to variably control the setting of said senders for controlling said mechanism.

“5. In a telephone exchange system, in combination, incoming lines, outgoing trunks, each trunk terminating at its distant end in a manually operable connection terminal, an operator’s position, a cord circuit terminating at each end in a manually operable device for interconnecting an incoming line and an outgoing trunk under the control of said operator’s position, means associative with the distant ends of said trunks for indicating the numbers of wanted lines, a plurality of senders for transmitting series of impulses of varying characteristics over said trunks for controlling said mechanism, registers in said sender for recording the digits of wanted line numbers, and means at said operator’s position to control the automatic selection of a trunk and of a sender and for variably controlling the setting of said registers for controlling said mechanism.

“6. In a telephone exchange system, a plurality of operators’ positions, a sender controlling equipment at each of said positions, a plurality of outgoing trunks, each trunk terminating at its distant end in a manually operable connection terminal, mechanism associative with the distant ends of said trunks for indicating the num-

bers of wanted lines, a plurality of senders, a plurality of sender controlling equipments, a plurality of switching units common to said operators' positions, means to operate a switching unit to establish an interconnection between a sender controlling equipment, a sender and an idle trunk, means to operate said mechanism over said trunk under the control of a sender in accordance with the operation of said sender controlling mechanism, and means operative following the completion of the operation of said sender to release said switching unit.

"7. In a telephone exchange system, a plurality of operators' positions, a sender controlling equipment at each of said positions, other operators' positions, a plurality of outgoing trunks, said trunks terminating at said latter positions in manually operable connection terminals, mechanism associative with the distant ends of said trunks for indicating the numbers of wanted lines, a plurality of senders, a plurality of sender controlling equipments, a plurality of switching units common to said first operators' positions, means to operate a switching unit to establish an interconnection between a sender controlling equipment, a sender and an idle trunk, means to operate said mechanism over said trunk under the control of a sender in accordance with the operation of said sender, controlling mechanism, and means operative upon the response of a second mentioned operator to start said sender into operation."

"9. In a telephone exchange system, a plurality of incoming lines, a plurality of outgoing trunks, each trunk terminating at its distant end in a manually operable connection terminal, means for interconnecting said lines and trunks, mechanism associative with the distant ends of said trunks for indicating the numerical designation of a desired line, a register sender, groups of relay registers for said sender, means for registering the numerical and stations designations of a desired line on said registers, means associated with said sender for transmitting over said trunks a plurality of series of impulses of varying characteristics corresponding to the designations registered on said registers for controlling said mechanism, and means for changing the order of transmission of said series of impulses in accordance with the operated condition of the relays of certain of said registers."
